UNITED STATES PATENT OFFICE.

TALBOT C. DEXTER, OF PEARL RIVER, NEW YORK.

PAPER-FEEDING MACHINE.

SPECIFICATION forming part of Letters Patent No. 623,769, dated April 25, 1899.

Application filed December 28, 1896. Serial No. 617,263. (No model.)

To all whom it may concern:

Be it known that I, TALBOT C. DEXTER, a citizen of the United States, residing at Pearl River, in the county of Rockland and State of New York, have invented certain new and useful Improvements in Paper-Feeding Machines, of which the following is a specification.

My invention relates to improvements in paper-feeding machines of the buckling type, in which the successive sheets of paper in an adjustably-supported pile are buckled and separated from the pile and then fed off from the pile to a printing-press, paper folding or ruling machine, or other machine designed to operate upon the paper.

The object of my invention is to improve the structure and operation of the several essential parts of such mechanisms to render such machines more accurate in separating the sheets, more effective in guarding against the delivery of more than one sheet, and more completely automatic in operation, and to provide means for arresting the movements of the several devices in cases when the sheets are not properly separated or the machine is otherwise imperfectly operating and would be liable to injure the mechanism or the sheets being handled.

To these ends my invention relates, first, to the improved buckling devices comprising an automatically-controlled spring-pressed holding-down finger engaging the corner of the pile of paper and an inwardly-reciprocating buckling-carriage carrying a loosely-journalized spring-pressed buckling-finger operated by suitable mechanism, which first releases the buckling-finger to the action of its spring to throw it down into engagement with the top sheet of the pile of paper and then engages the reciprocating carriage for moving the finger inwardly for buckling the sheet. The reciprocating carriage of the buckler is provided with a spring-pressed brake, which overcomes the initial tendency of the carriage to move at each change of direction, for the purpose of giving the buckling-finger time to move into contact or out of contact with the paper before the movement of the carriage.

My invention consists, secondly, in providing friction-blocks, which constantly rest upon the pile of paper and exert an effective

frictional resistance upon the under sheet or sheets at their rear edge or edges, which may by chance be buckled and started off from the pile together with the top sheet in order that said under sheet or sheets will be held back while the top sheet is carried off by the feeding-off devices and drop-rollers. These friction-blocks assist greatly in separating the sheets when more than one sheet is started off, because in such cases the underlying sheet or sheets will almost invariably project slightly back of the upper sheet and allow said blocks to engage the rear edge or edges of said under sheet or sheets, and, although each of said underlying sheets may not project more than one-eighth of an inch, the friction between the under sheets and the friction-blocks will be greater than the friction between the two smooth sheets of paper, and consequently the under sheets will be effectively held back while the upper sheet is fed off. I consider this device of great importance.

My invention consists, thirdly, of automatically-operated holding shoes or blocks which are forcibly thrown down into engagement with the pile of paper directly in rear of the rear edge of the top sheet just as it is fed off to its most forward position by the main separators and is in position to be grasped by the drop-rollers for the purpose of further counteracting the tendency of the frictional engagement between the top sheet and the pile to carry forward more than one sheet. These holding-down blocks are so adjusted that they will just miss the rear edge of the top sheet and firmly engage the next underlying sheet and hold it back even though said underlying sheet has been advanced so far that the friction between it and the top sheet would be sufficient to carry it forward into the bite of the drop-rollers. It often happens that the main separators at the delivery end of the machine will separate the top sheet from the underlying ones, but will advance the underlying ones so near to the drop-rollers that they are liable to be drawn forward. These holding-down blocks are important for preventing this.

My invention consists, fourthly, in an improved governing device for automatically regulating the height of the pile of paper.

This governing device comprises, essentially, an intermittently - operable driving - shaft 5 geared to the table-elevating screws and having a ratchet-wheel keyed to it which is operated by a pawl carried upon an intermittently-oscillated rock arm or lever loosely journaled upon the driving-shaft, a hood or shield being also loosely journaled upon said shaft and constructed and arranged to project over a 10 segment of the teeth of the ratchet-wheel for holding the pawl out of engagement with the ratchet-wheel while the pile of paper is at its proper height. The hood is connected through a suitable link with a vertically-sliding gage-rod which is normally held in elevated position by means of a dog formed upon a bell-crank lever pivoted to the machine-frame and carrying at its lower end a freely-journaled roller which rests upon the top of the pile of 15 paper. Said hood or shield is also connected through suitable links, crank-arms, and a rock-shaft with the pawl-carrying rock-arm in such a manner that the hood or shield will be oscillated over the teeth of the ratchet-wheel, exposing some of the teeth of the ratchet-wheel to the action of the pawl and causing the gage-rod to move up and down in its bearings when the surface of the pile of paper has descended sufficiently below the 20 normal plane to disengage the dog from said gage-rod. When the pile of paper is at its normal height, suitable springs hold the hood or shield in normal position to keep the oscillating pawl out of engagement with the ratchet-teeth, and during this normal position of the mechanism the continued regular oscillation of the pawl-carrying arm will not move the shield and connected gage-rod, because the engagement between the two parts 25 of the mechanism is effected by means of a tappet or collar on the operating-rod of the shield and a head attached to the oscillating pawl-carrying rock-arm, which slides upon said rod and only engages the tappet when 30 the gage-rod has been allowed to fall below normal by the disengagement of the dog caused by the lowering of the pile of paper.

My invention consists, fifthly, in the construction of the feeding-off devices comprising, essentially, a reciprocating carriage, upon which are pivotally mounted a plurality of spring-pressed feeding-off fingers, (one behind the other,) which are thrown into engagement with the surface of the top sheet of paper by the action of their springs and automatically elevated from the paper by means of a longitudinally-sliding rack-bar movably mounted upon the carriage and having a lower cam - face engaging vertically-sliding rods, 55 which in turn engage the feeding-off fingers. When the rack-bar in the carriage is in normal position, the feeding-off fingers are in engagement with the surface of the top sheet of paper, but as soon as the forward edge of 60 the sheet being fed off reaches proper registered position it actuates an electric contact device and an electric circuit is broken and

a pawl or dog thereby released by an electro-magnet to fall into engagement with the rack-bar, causing said rack-bar to be held stationary while the reciprocating feeding-off carriage continues to move, resulting in the elevation of the feeding-off fingers from the surface of the paper. As long as a sheet of paper is passing between the controlling contact devices the pawls or dogs are in engagement with the rack-bars, thereby holding the feeding-off fingers up from the surface of the paper. As soon as the sheet is fed off and the contacts of the controlling circuits are again made the dogs are drawn up out of engagement with the rack-bars, which are shifted to normal position to allow the feeding-off fingers to again operate. In addition to the automatic control of the rack-bars suitable stops are provided to engage the rack-bars at the forward and rear end of the movement of the feeding-off carriages to throw the rack-bars back into normal position, the normal position being such that the feeding-off fingers will be held out of engagement with the surface of the paper during the rearward stroke of the carriages.

My invention consists, sixthly, of the combination of a suitable sheet-retarding bed located at the delivery end of the machine, a frictional separator operating upon the sheets of paper over said bed to carry the top sheet over the bed and separate it from any chance underlying sheets, and an independent auxiliary feeding-off instrument operating upon the pile of sheets at the rear of the separator-pad to feed off the top sheet from the pile onto the sheet-retarding bed before said sheet is engaged by the separating-pad. The feeding-off instrument and separating-pad operate upon the sheets alternately or successively, the feeding-off instrument first pushing the sheet forward to the bed and the separator-pad then engaging the sheet on the bed. It is not necessary that the feeding-off instrument shall disengage the sheet the moment the separator - pad comes into engagement with it, as their operations may slightly overlap or be partly coincident; but it is essential that they should be brought into play alternately or successively to produce the important result aimed at in this part of my invention. I also prefer to employ suitable sheet-delivering mechanism to convey the successive advanced sheets from the sheet retarding or separating beds of the machine to the printing-press, folder, or other machine.

My invention consists, seventhly, in the improved separating device located at the delivery end of the machine and operating, in conjunction with the independently-operated feeding-off devices, in accordance with the fifth part of my present invention, to receive the sheet being fed off and separate therefrom any additional under sheet or sheets which may by chance have passed the bucklers and resistance-brakes, causing the upper sheet to be fed to the drop-rollers or other

sheet-delivery mechanism of the machine and holding back said under sheets. The separator comprises a paper-retarding bed disposed at the delivery end of the machine and having an upper friction-surface to which the forward edges of the sheets of paper are delivered by the feeding-off devices and a friction pad or block reciprocating over said retarding-bed and moving vertically to and from it at the ends of its stroke and adapted to engage the top sheet and push it forward over the bed while the underlying sheet or sheets is or are detained by their frictional engagement with the bed. Suitable sheet-delivering mechanism, such as the drop-rolls shown, engage the separated sheet, which is pushed forward over the retarding-bed of the separator, and convey it from the machine. The operating mechanism of the reciprocating friction pad or block of the separator has a twofold function, as in the operating mechanism of the buckler, in that it first moves said friction-pad into or out of engagement with the surface of the paper and then by continued movement in the same direction causes the reciprocation of the carriage either forward or backward, an automatic spring-brake being provided to counteract the initial tendency of the carriage to move and give time for the supporting-block to move into or out of engagement with the paper before the reciprocation of the carriage.

The invention consists, eighthly, in arranging the sets of feeding-off devices and separating devices one behind the other in groups which are connected by a suitable structure to enable the ready adjustment of each group transversely of the machine to suit the requirements for operating upon the paper of different sizes. To accomplish this result, the track-bars upon which the feeding-off carriages and separator-carriages reciprocate are supported at their ends upon castings which slide upon the frame-pieces, while the operating levers and links are supported from another casting connected with one of the aforesaid castings, and the cams for effecting the movements of the operating-levers are keyed to a suitable sleeve having a sliding spline connection with the operating-shaft, which sleeve is formed with an annular groove in which engages a fin or flange projecting up from one of the castings. In this way all of the parts of each group of mechanisms are readily adjusted at one time by simply loosening one or more securing-bolts in one of the main castings. In the machine illustrated in the drawings two sets or groups of such mechanisms are employed, one at each side of the machine, each set comprising a feeding-off mechanism and a separating mechanism.

My invention consists, ninthly, in providing means for automatically arresting the operation of the machine in cases when the several mechanisms have for unseen reasons failed to properly separate the sheets and

have fed forward a greater number of sheets than the separating devices can effectively manage. It will be clear that such an arrangement is very important in this class of machines. The separating devices can effectively separate from four to six sheets when they are passed forward to them; but if a greater number of sheets are fed forward there is not sufficient room upon the lower retarding-bed to effectively engage the forward edge of all of the sheets, and consequently two or more sheets will be engaged by the drop-rollers and conveyed to the folder or printing-machine, causing the destruction of such sheets and sometimes the injury of the machine. To obviate this difficulty, I have provided an automatic clutch device which disengages the machine from the power-shaft and positively arrests its movement when an electric contact device is actuated by the thickness of more than the maximum number of sheets which the separator can properly take care of, said contact device closing a circuit which energizes an electromagnet, causing the operation of the operating-arm of the clutch-controller. A hand-lever is also provided, which engages the clutch-controller for throwing the machine out of operation by hand. To further insure the positive stopping of the machine under the action of the automatic clutch, I provide a rock-arm connected to said clutch-controlling mechanism and provided with a dog or lug which engages a similar dog or lug on one of the supporting rock-arms of the drop-rollers in order that said drop-rollers will be held out of operation the instant the machine is stopped, to thereby prevent any slight forward feed of the paper by their momentum.

My invention consists, lastly, in various combinations of the parts above referred to and in certain minor details of construction of the several parts of the machine, which, together with the features above pointed out, will first be described with reference to the accompanying drawings, forming part of this specification, and afterward more particularly pointed out with respect to their patentable novelty in the annexed claims.

In said drawings, Figure 1 is a plan view of the left-hand portion of my improved feeding-machine. Fig. 2 is a plan view of the right-hand portion of the same. Figs. 1 and 2 taken together represent a plan view of the whole machine. Fig. 3 is a detail perspective view of part of the rear right-hand corner of the machine. Fig. 4 is a front perspective view of the sheet-buckling mechanism and one of the air-blast devices. Fig. 4^a is a detail sectional view showing the friction-brake of the buckling devices. Fig. 5 is a detail perspective view showing the paper-retarding brake and the holding-down shoes or blocks. Fig. 5^a is a detail transverse sectional view showing the means for operating the holding-down shoes or blocks. Fig. 6 is a perspective view of the governor mechan-

ism for regulating the height of the paper-supporting table. Fig. 7 is a longitudinal sectional view of the machine, showing the paper-table-governing mechanism and operating devices. Fig. 8 is a perspective view of one of the feeding-off devices and its controlling mechanism. Fig. 9 is a detail longitudinal sectional view of the machine, showing the same devices. Fig. 10 is a detail perspective view of the paper-separator and feeding-off devices, showing also the electric controller of the feeding-off devices. Fig. 11 is a detail perspective view of one of the separating devices, looking at the opposite side from that represented in Fig. 10. Fig. 12 is a top perspective view of one set of the feeding-off devices and separator, showing particularly the castings for supporting them in an adjustable set or group. Fig. 13 is a detail longitudinal sectional view of the driving-shaft, showing the arrangement of the operating-cams upon the adjustable sleeve for operating the feeding off and separator devices. Fig. 14 is a front perspective view of the electric contact device controlling the main clutch of the machine and also showing paper-guides and one of the paper-feeding drop-rollers. Fig. 14^a is a detail front elevation of said contact device. Fig. 15 is a perspective view showing the main driving-gear and clutch with the automatic mechanism for throwing the same out of gear and arresting the operation of the machine. Fig. 16 is a perspective view showing the automatic means for supporting the drop-rollers in inoperative position and the gearing for operating them. Fig. 16^a is a detail elevation illustrating, diagrammatically, the gearing from the main driving-shaft to the drop-rollers. Fig. 17 is a detail side elevation of parts of the feeder and a folding-machine to which the feeder is geared, showing the adjustable device for gearing the feeder to any machine. Fig. 17^a is a detail transverse sectional view taken on line xx of Fig. 17. Fig. 18 is a diagrammatic representation of my improved feeding-machine, representing the relative positions of the several mechanisms.

Like letters and numerals of reference indicate the same parts throughout the several views.

1 1 are the side pieces or bars of the main frame, formed, preferably, of channel-iron, and 2 5 are the front and rear bars, connecting the side frame-pieces. The bars 2 and 5 are preferably of angle-iron. Extending between the top side pieces 1 1, parallel with the angle-iron frame-pieces 2 and 5, is the channel-iron frame-piece 3, all of which parts are securely bolted together to support the mechanisms hereinafter to be described.

6 is the vertically-movable paper-supporting table, upon which is piled the paper P. The paper-supporting table operates within suitable vertically-extending paper-guide rods of usual construction, (not shown,) and is provided with outwardly-extending thread-

ed ears or lugs p, working in vertical slots 12^a in standards 12, through which ears or lugs work the vertically-extending adjusting-screws 7. (Indicated by dotted lines in Figs. 1 and 2.) Keyed to the upper ends of the vertical screws 7 are bevel cog-gears 8, with which mesh the similar bevel cog-gears 9, keyed to the transverse shaft 10 adjacent to its ends, which shaft is journaled in bearings 11 on the main side bars 1 of the machine-frame.

It will of course be understood that the main frame-pieces 1 1 are supported at the upper ends of suitable standards or vertical side-frame pieces, such as 12, as indicated in detail view Fig. 3. Extending rearwardly from the vertical side frame-pieces 12 are the auxiliary track-bars 13 of dovetailed cross-section.

14 and 15 are brackets extending inwardly from the side bar 1 and auxiliary frame-piece 13, respectively, and 16 is an adjusting-screw journaled in the brackets 14 and 15 and formed with a worm-gear 17, with which meshes a similar worm-gear 18, keyed to an adjusting-shaft 19, journaled in the side bars of the machine and extending at a right angle to screw 16 from side to side of the machine.

20 is an operating crank-handle keyed to shaft 19, by means of which said shaft is rotated.

25 is a head embracing the bar 13 so as to slide thereon, and 26 is a lug or block projecting inwardly from the head 25 and formed with a threaded opening through it, through which passes the shaft 16.

It will be observed that there is a bar 13 supporting a head 25 and an adjusting-screw 16 at each side of the machine. Extending between the heads 25 and supported by them is an auxiliary frame piece or bar 27. Bolted to the lugs 26 and journaled in bearings 28, projecting upwardly from heads 25, is the rotary buckler-operating shaft 29. Upon the bar 27 and shaft 29 (which are adjustable longitudinally of the machine by the movement of the heads 25) are adjustably mounted two sets of sheet-buckling devices, two sets of paper-retarding brakes, and two paper-holding shoes or blocks, which will be described in their order, and as both sets of each pair of such devices are of the same construction a description of but one set of each will be given, as this will be sufficient for a proper understanding of the whole.

30 is a casting formed with engaging lugs 31, by means of which it is adjustably mounted upon the bar 27. The rear face of the casting 30 is formed with guide-flanges 32, between which slides the reciprocating buckler-carriage 33. The sliding carriage 33 has projecting out from its rear face a rigidly-secured bolt 34, having a head 35 at its outer end.

36 is the buckling-finger, having a forward bifurcated end 37, in which is rigidly clamped the rubber-faced buckling-roll 38. The buckler-finger 36 is loosely journaled upon the bolt

34 and is given a tendency to press against the top of the pile of paper by means of the spiral spring 39, having an end 40 engaging the buckler-finger and its opposite end engaging the head 35.

41 is a bell-crank lever loosely journaled upon the bolt 34 between the buckler-finger 36 and sliding block or carriage 33, and 42 is a right-angled projection on the bell-crank lever, which extends under the spring-pressed buckling-finger 36, engaging with said finger for elevating it against the action of the spring 39.

43 is a lug formed integral with the sliding block or carriage 33.

45 is a journal-pin projecting out from the vertical plate 30^a of the casting 30, and 46 is a lever pivoted upon the pin 45 and having its lower end connected to the upper end of bell-crank lever 41 by means of a short link 47.

48 is a double-faced cam adjustably keyed to the shaft 29 and engaging an antifriction-roller 49, journaled upon the upper end of the lever 46. By the rotation of the cam 48 the lever 46 will be rocked to cause the bell-crank lever to move, throwing its vertical arm over into engagement with the lug 43 and releasing the buckling-finger 36 to the action of its spring 39, which throws it down upon the surface of the pile of paper. As soon as the vertical arm of the lever 41 engages lug 43 the buckler slide or carriage 33 will be moved inwardly by the continued movement of lever 46, causing the corner of the sheet of paper to be buckled. The bolt 34 also projects forwardly from the carriage 33 and extends through the slot 30^b of casting 30.

33^a is a leather-faced brake-block loosely supported upon bolt 34 and held in frictional engagement with the casting 30 by means of a spiral spring 34^a and clamp-nuts 34^b. This brake overcomes the initial tendency of the buckler-carriage to move and exerts sufficient resistance to insure the moving of the buckler-finger into or out of engagement with the sheet before the reciprocation of the carriage.

Supported in bearings 50 and 51 of the casting 30 is a vertically-movable rod 52, having a spiral spring 53 surrounding it and engaging the upper bearing 50 at one end and a head 54 at its lower end, which head 54 is loosely mounted upon the rod 52 above an adjustable collar 55 on said rod and is held down against said collar by the spring 53. Projecting upwardly from the head 54 is an arm 56, to the upper end of which is pivoted a crank-arm 57, formed integral with a head 58, from which projects another crank-arm 59, having journaled at its upper end an antifriction-roll 60. 61 is a single-faced cam adjustably keyed to the shaft 29 alongside of cam 48 and engaging the antifriction-roll 60 to cause the intermittent lifting of the head 54 for releasing the spring-pressure upon the rod 52. The lower end of the rod 52 is provided with a paper retaining or holding-down foot 52^a, which constantly rests upon the extreme cor-

ner of the pile of paper and holds the pile intact while the sheet which has been buckled is being fed off, the pressure upon the holding-down foot being released (without elevating the foot from the pile) just as the corner of the top sheet is buckled and slid from under said foot and being allowed to act again as soon as the edge of the sheet has been withdrawn from under the foot. As the holding-down foot always rests upon the surface of the pile, though only by its own gravity, while the corner of the top sheet is being buckled, the liability of buckling more than one sheet 80 and the chance of the buckled corner of the sheet slipping back under the holding-down finger are greatly reduced. The spring-pressure is normally on the holding-down finger, during which time the buckled sheets are being fed off from the pile.

Bolted to a horizontal flange 30^c of the casting 30 is a plate 62, having vertical flanges 63, having bearings 64, through which the shaft 29 passes.

65 and 66 are collars mounted upon the shaft 29 upon the opposite sides of the bearing-lugs 63 for securing the same in place. By simply removing the screws from the collars 65 and 66 the casting 30 and plate 62 can be shifted transversely of the feeding-machine, the casting 30 sliding upon the bar 27 and the cams 48 and 61 sliding upon the shaft 29, carrying all of the operating parts of the buckler with them. By means of this lateral adjustment and the longitudinal adjustment already described the position of the buckling devices can be regulated to a nicety to suit sheets of paper of any size.

70 is a main air-pipe adapted to receive air from any suitable blower. (Not shown.) The air-pipe 70 is supported by brackets 71 from the side frame-pieces and is provided at proper intervals in its length with the couplings 72, from which extend the nozzles 73, provided with cocks 73^a.

74 are flexible air-pipes extending from the nozzles 73 to the air-supplying nozzles, which are supported at the proper points to supply air-blasts under the top sheet as soon as it is buckled preparatory to being separated from the pile.

75 are suitable adjustable brackets supported upon auxiliary frame-piece 27 and secured in any adjusted position by means of the screws 76.

75^a are slotted arms extending from brackets 75, and 77 is the air nozzle or pipe connecting with flexible pipe 74 and provided with an adjustable rod 78, which is adjustably secured in the slotted arm 75^a by means of the device 79. The lower end of nozzle or pipe 77 is curved inwardly and flattened to supply the blast in a plane horizontal to the surface of the pile of paper. It will be observed that nozzles 77 are represented adjacent to each of the buckling devices and at each side of the pile, as hereinafter referred to.

80 are adjustable brackets embracing rod

27 and have journals 81, in which are journaled the rock-shafts 82, having keyed upon their rear ends the arms 83. Pivotedly mounted in the lower end of arm 83 is a long narrow 5 paper-retarding brake-block 84, carrying a rubber friction-pad 85.

86 is a spiral spring surrounding rock-shaft 82 and engaging a head 87 (indicated by dotted lines) at one end and the bearing 81 at 10 the other for constantly holding the brake-block 84 in engagement with the surface of the paper. The purpose of the brake-blocks 84 is to exert an effective resistance upon the rear edges of the under sheets of paper in cases 15 where two or more sheets are separated by the buckling devices and start off together, with the upper sheet a little in advance of the under one. That this result may be accomplished the blocks are formed very narrow and the springs 20 are adjusted to exert only a light pressure upon them, so that the frictional hold of the brake-blocks upon the top sheet will be inferior to the frictional hold of the feeding-off instruments, but will be sufficient upon the 25 rear edges of the under sheets to counteract the friction between the sheets.

90 is a bracket adjustably supported upon bar 27, formed with a bearing 91, in which slides the vertically-movable square rod 92, carrying an adjustable tappet or collar 93, adjacent to its upper end.

94 is a rod adjustably mounted in an opening formed in the lower end of the rod 92 and held rigidly therein in adjusted position by 35 a set-screw 92^a, and 95 is a holding shoe or block pivoted to the forward end of rod 94.

96 is a cam adjustably keyed to shaft 29 and confined between the bearings 97, projecting up from the plate 98, which is bolted 40 to the horizontal flange 90^a of the bracket 90.

98^a is an integral arm projecting from the plate 98, formed with a bearing in its end.

100 is a vertically-extending rounded rod passing through the opening or bearing in arm 45 98^a and pivotally attached at its lower end to the lower end of the square rod 92.

101 is a spiral spring surrounding rod 100 and confined between the arm 98^a and an adjustable collar 102. The purpose of rod 100 50 and spring 101 is to exert a downward pressure upon the rod 92, it being preferable to provide the rounded rod 100 with its surrounding spring 101 than to surround the square rod 92 with a spiral spring, because in the latter case the spring would bind and interfere with the free movement of the square rod 92.

103 is a short lever pivoted at 104 and having a foot 105 at its forward end, which engages a tappet 93 on rod 92, and such lever 60 projects beneath the cam 96, by which it is operated for holding rod 92 and shoe or block 95 normally upward and for intermittently releasing them to allow spring 101 to throw block 95 into engagement with the surface of the 65 pile of paper just behind the rear edge of the top sheet for holding the under sheets and preventing them from being drawn off by the

friction of the sheet being fed off. The holding-down shoes or blocks may be adjusted as a whole with the other mechanisms described by the adjustment of the heads 25, carrying bar 27 and shaft 29, or they may be individually adjusted by means of the adjustment of rod 94 in rod 92. The blocks or shoes 95 are pivotally attached to rods 94 to enable them to 75 automatically conform to the upper surface of the pile when they are pressed down by spring 101.

As stated above, the shaft 10 engages the vertically-threaded shafts 7 by means of intermediate gears 8 9 to cause the intermittent elevation of the table supporting the paper.

I will now describe the automatic mechanism for governing the elevation of the table as the paper is fed off.

110 is a ratchet-wheel keyed to the shaft 10, and 111 is a rock arm or lever journaled upon shaft 10 adjacent to the ratchet-wheel 110.

112 is an operating rod or pitman journaled at 113 to the rock arm or lever 111 and having formed upon its forward end a guide-loop 114, which embraces the main power-shaft 115, hereinafter more fully described.

116 is an oval-shaped cam keyed to the shaft 115, and 117 is an adjustable collar, also keyed to the shaft 115, the loop end 114 of the rod or pitman 112 being confined and guided between said cam and collar.

118 is an antifriction-roller journaled to the rod 112 adjacent to the inner end of the guide-loop 114, with which the cam 116 engages for reciprocating rod 112 to cause the oscillation of the rock arm or lever 111.

119 is a spring-pressed pawl journaled upon a journal-pin 120 and adapted to engage the teeth of the ratchet-wheel 110 for causing the partial rotation of the shaft 10, which in turn imparts rotation to the vertical shafts 7 for elevating the paper-carrying table.

121 is a rod pivoted to the pitman 112, adjacent to its lower end and extending rearwardly through an opening 122 in the angle-iron frame-piece 5, and 123 is a long spiral spring surrounding rod 121 and confined between angle-iron 5 and an adjustable collar 124, by means of which the tension of spring 123 can be adjusted. The purpose of the spring 123 is to keep the antifriction-roll 118 constantly pressed against the operating-cam 116.

The mechanism as above described would cause the elevation of the table a short step at each oscillation of the pawl-carrying lever 111, which would be entirely too much for the proper operation of the machine. It is therefore very desirable to provide automatic mechanism controlled by the height of the pile of paper for regulating the action of the table-elevating mechanism. To accomplish this, I have devised the following mechanism:

125 is a segment-shaped hood or shield formed with a semicircular flange 126 and the hub portion 127. The hood or shield is journaled upon the transversely-extending table-

elevating shaft 10, adjacent to the ratchet-wheel 110, with its semicircular flange 126 covering a portion of the toothed periphery of the ratchet-wheel, the spring-pressed pawl 119 being adapted to ride upon the flange 126 during the greater part of its stroke forward and back.

128 is a rock-arm secured to and projecting from the hub 127 of the hood, and 129 is a slot formed in said arm.

130 is a frame-piece rigidly secured at its forward end to a bracket 131, bolted to the channel-bar 3 and at its rear end to the bracket 132, which embraces the angle-bar 5.

5 The frame-piece 130 is shaped to suit the position it assumes in the main frame and has projecting upwardly from it a suitable bearing-block 134, through which the table-elevating shaft 10 passes. The purpose of this 20 is to strengthen and steady the supporting frame 130.

135 is a rock-shaft journaled in the frame-piece 130 and having keyed to one end a slotted rock-arm 136 and to its other end a rock-arm 137. The rock-arm 137 has a rod 138 pivoted to it and projecting rearwardly through a sliding head 139, which is pivotally attached to the lower end of the lever 111 by means of the pivot-bolt 140.

30 141 is an adjustable tappet or collar secured to the rearwardly-extending rod 138 in proper position to be engaged by the sliding head 139 at such times when the hood or shield 125 is to be shifted for the purpose and in the manner which will hereinafter appear.

142 is a rod having adjustable connections 143 and 144 with the slotted crank-arm 136 and rock-arm 128, respectively, for connecting hood 125 with rock-shaft 135.

40 145 is a rod pivoted at 146 to crank-arm 136 and projecting rearwardly through a guide-bracket 147, secured to the frame-piece 130.

148 is a spiral spring surrounding the rod 145 and confined between a collar 149 and the 45 bracket 147 for holding the hood and its connected operating parts in normal position.

150 is a guide-bracket bolted to the angle-iron frame-piece 5, and 151 is a square vertically-sliding gage-rod sliding in bearing-openings formed in the bracket 150 and frame-piece 5.

152 is an adjustable head or collar clamped to the rod 151 by screw-bolt 153.

154 is a pitman or connecting-link pivoted 55 at its upper end 155 to the hood or shield 125 and pivoted at its lower end 156 to the head 152, secured to rod 151.

157 is an adjustable collar secured to rod 151 and adapted to engage the frame-piece 5 60 for limiting the downward movement of the rod 151.

158 is a bracket adjustably secured to the angle-iron frame-piece 5, and 159 is a bell-crank lever pivoted in ears 160 of the bracket 65 158 and formed with an integral dog 161 on its vertical arm and having an antifriction-

roller 162 freely journaled in the bifurcated lower end of its other arm.

163 is a notch cut in the forward face of gage-rod 151, in which the dog 161 is adapted 70 to engage for preventing the downward movement of the gage-rod and holding the guard or shield in position to prevent the operation of the table-elevating mechanism.

The operation of this table-governing mechanism will be clear from the following explanation: As long as the top surface of the pile of paper is at the proper elevation the dog 161 will engage notch 163 and hold gage-rod 151 and hood 125 in normal position, and the tappet 141 on the rearwardly-extending rod 138 will be out of reach of the head 139, carried by rock-arm 111, which is constantly oscillated by its operating-cam. In this position of the parts the hood 125 will hold pawl 119 out of 85 engagement with the teeth of ratchet 110, and the height of the pile will not be changed.

Just as soon, however, as sufficient paper has been fed off to lower the surface of the pile far enough to disengage dog 161 from notch 90 163 (by lowering of rock-arm 159) the gage-rod 151 will fall to the limit of its stop and allow spring 148 to shift hood 125 rearwardly, and thereby uncover the teeth of ratchet 110 to the pawl 119.

The rod 138, carrying tappet 141, will also be moved rearwardly when the hood is shifted, thus throwing tappet 141 into the path of head 139. The forward stroke of the pawl having partially rotated ratchet 110, the rock-arm will move back and cause 100 head 139 to engage tappet 141 and shift rod 138 forwardly, which through the connections described will shift hood 125 forwardly and raise gage-rod 151 against the action of spring 148. Now if the partial rotation of ratchet 105 110 has been sufficient to elevate the pile of paper to the required plane the dog 161 will be ready to slip into notch 163 as soon as gage-rod 151 is raised; but if the paper is not high enough the spring 148 will cause hood 125 and 110 gage-rod 151 to again shift with the succeeding forward movement of pawl 119, the tappet 141 following head 139 rearwardly into position to be again engaged by said head. This 115 operation again uncovers the ratchet-teeth to the action of the pawl. These steps are repeated till the paper is elevated sufficiently high to hold dog 161 in notch 163, which holds the pawl 119 out of engagement with ratchet 110 and tappet 141 out of reach of head 139 120 and does not interfere with the regular oscillation of pawl-carrying arm 111 under the action of its cam.

In addition to the air-blast nozzles 77, supported at the rear of the pile, as above described, I provide an air-nozzle 165 at each side of the pile of paper for directing currents of air under the top sheet of paper at the sides and more completely separating it from the pile. The air-nozzles 165 connect 125 with flexible branch pipes 74 and are supported in positions by brackets 166 from the 130

frame-piece 5 in the same manner that the air-nozzles 77 are supported.

As soon as the top sheet of paper has been buckled and partially separated from the pile by the devices above described it becomes necessary to feed the sheet forward from the pile without twisting or turning it in order that it will pass squarely to the printing-press, folder, or other machine and require the least possible registering. To accomplish this, I provide two sets of feeding-off devices, one adjacent to each side of the machine and each comprising a reciprocating carriage carrying two feeding-off fingers arranged one behind the other. The construction of these devices will now be described.

170 is a track-bar bolted at its forward end to a bracket 171, (of peculiar construction, hereinafter more fully explained,) which is 20 adjustably mounted upon the forward angle frame-bar 2 and at its rear end to a bracket 172, having sliding connection with the angle frame-bar 5.

175 is the feeder-off carriage, formed with 25 integral lugs 176, which embrace the bar 170 and allow the carriage to slide thereon.

177 are vertically-extending guide arms or lugs depending from the carriage 175 and formed with vertical guide-grooves, in which 30 are supported the vertically-sliding rods or plates 178, said rods being confined in the grooves by the plates 179, secured by screws 180. The lower ends of the depending guide-arms 177 are formed with bracket-arms 181, 35 in which are pivotally mounted the feeding-off fingers 182, said feeding-off fingers having the rubber-surfaced feed-rolls 183 rigidly secured in their forward bifurcated ends 184. Projecting rearwardly from the journal portion 185 40 of each of the feed-fingers 182 is a heel 186, having a pin 187, with which the lower slotted or bifurcated end 188 of one of the rods or bars 178 engages. There is lost motion or a loose joint between each pin 187 and rod or bar 178 45 to allow the springs of the feed-fingers more freedom and for forcing the feed-fingers down into engagement with the surface of the paper to insure the proper frictional engagement of the fingers with the paper whether the paper 50 is soft and gives considerably or is stiff and unyielding. This feature is a very important one.

189 is a pivot-rod or journal-pin secured to and projecting from the hub portion 185 of 55 the feeding-off fingers through one of the bracket-arms 181 and provided with a head 190 at its end.

191 is a spiral spring surrounding the rod 189 and engaging the head 190 at one end 60 and one of the bracket-arms 181 at its other end for the purpose of causing the feeder-off fingers to be pressed against the surface of the paper with a yielding pressure. Formed integral with the upper end of each of the 65 rods or bars 178 is a bifurcated portion 192, in which is journaled an antifriction-roller 193.

As above stated, each feeding-off carriage

supports two feeding-off fingers constructed as just described.

The antifriction-rollers 193 bear upon the 70 lower surface or cam-face of a rack-bar 194, which is formed with two longitudinally-extending slots 195, the rack-teeth 196 on its upper surface, and the semicircular recesses 197 in its lower or cam surface. The semicircular recesses 197 are arranged the same distance apart as the antifriction-rollers 193 in order that said rollers may enter said recesses when the rack-bar is in the proper position, and thereby allow both of the rods or bars 178 80 to move upwardly in their bearings at the same time to permit the springs 191 to throw both of the feeder-off fingers down into operative engagement with the surface of the sheet being fed off. 85

178^a is a wire spring supported centrally upon a screw 175^a, secured to the feeder-carriage and having its opposite ends engaging the shoulders formed near the upper ends of rods or bars 178 by the bifurcated portions 90 192. The purpose of the spring 178^a is to keep the rollers in contact with the lower surface of rack-bar 194. Embracing the rack-bar 194 are the lugs 198, which are integral with the feeder-off carriage 175 and extend upwardly 95 upon the opposite faces of the rack-bar.

199 are antifriction-rollers working in the longitudinal slots 195 of the rack-bar and journaled between the integral lugs 198 of the feeder-off carriage, the purpose of said lugs 100 198 and rollers 199 being to confine the rack-bar within proper limits upon the feeder-off carriage.

200 is a lug depending from the feeder-off carriage 175, and 201 is a connecting-link pivoted to lug 200 at one end and to the lower end of the operating-lever 202 at its other end, which operating-lever 202 is pivotally supported at its upper end 203 from the rearwardly-curved horn or bracket-arm 204, projecting from and forming part of the casting or bracket 205, which embraces and is supported upon the channel-bar 3. The bracket or casting 205 is adjustably mounted upon the frame-piece 3, as will be hereinafter more 110 fully explained. 115

206 is an operating rod or pitman pivoted at 207 to the lever 202 and formed with a guide-loop 208 at its forward end, which guide-loop embraces the main shaft 115 upon one 120 side of the cam 209.

210 is an antifriction-roller journaled upon pin 212 upon the rod 206 at the outer end of the guide-loop 208, said antifriction-rollers being engaged by the cam 209 for moving the 125 rod 206 and lever 202 forward against the tendency of spring 216 for imparting the necessary reciprocating motion to the feeder-off carriage 175.

213 is a rod pivoted at 214 to lever 202 and 130 projecting forwardly through a guide-opening in bracket 215, secured to and extending up from the casting 205.

216 is a spiral spring surrounding rod 213 and

confined between bracket 215 and an adjustable collar 217 on rod 213 for holding the anti-friction-roller 210 in contact engagement with the cam 209.

5 It will be clear from the description of the parts of the feeding-off devices as far as gone that should the rack-bar 194 remain in normal position, with rollers 193 resting in recesses 197, the friction-blocks 183 of the feeder-off fingers 182 would be in constant engagement with the surface of the sheet to be fed off. This would be objectionable not only on account of the fact that it would be impossible to correct the position of or registry of 15 the sheet which has started forward slightly out of position, but because the friction of the block 183 upon the surface of the paper during the backward movement of the carriage would be so great that it would interfere with the movement of the sheets forward out of the machine. In view of this I have devised means for automatically shifting the rack-bar 194 to lift the friction-blocks 183 from the surface of the paper as soon as 20 they have fed the sheet forward to the proper point and for holding said friction-blocks elevated during the movement of the carriage backward. These means comprise a dog or pawl 220, journaled upon a pin 221, projecting from the horn or bracket-arm 204 and confined by the adjustable collar 222, a spiral spring 223, surrounding rod 221 and engaging the dog 220 for throwing it normally into engagement with rack 194, an armature 224, 25 formed integral with the dog 220, and an electromagnet 225, adapted to be excited by the electric current under the control of suitable contact devices actuated by the sheet of paper, as hereinafter described, for holding the dog 30 normally disengaged from the rack-bar and allowing it to drop into engagement therewith when the circuit is broken. The electromagnet 225 is supported from the casting 205 upon a bracket 225a.

45 230 is a bracket-arm having a right-angled projection 231, formed with a threaded head 232 at its forward end, in which head is adjustably mounted a small receptacle or cup 233, of metal, containing a small quantity of 50 mercury.

234 is a bracket-arm extending from bracket 230, and 235 and 236 are two arms of a contact device secured to a hub portion 237, which is pivotally mounted upon pointed 55 screws 238, adjustably mounted in brackets 230 and 234.

239 is a strengthening-rib extending between arms 235 and 236.

240 is a pin depending from the forward 60 end of arm 235 and dipping into the mercury contained in the metal cup 233. The lower forward end of arm 236 is turned or bent slightly, and the bent end rests in a shallow groove 241, formed on the upper face of the 65 plate 242, of fiber or other insulating material, secured alongside of the casting 243, which supports the lower block 244 of the separator.

Circuit-wires 245 lead from the contact devices to the main-circuit wires 247 and 248, leading from the small generator 249, the circuit-wire 245 including the electromagnet 225 above referred to. The structure of the electric contact-controlling device is substantially the same as that described and claimed in a patent granted to myself and Clarence 70 Ransom December 21, 1897, No. 595,768, for improvements in electric registering devices for paper-feeding machines. The contact device is normally in position to close the circuit through the electromagnet 225, causing 75 said magnet to attract the armature 224 and hold the dog 220 out of engagement with the rack 194. As soon, however, as the forward edge of the sheet of paper comes in contact with the arm 236 said arm will be lifted, causing 80 the circuit to be broken between pin 240 and mercury in cup 233, which will deenergize the magnet 225 and allow the dog or pawl to drop into engagement with the rack-bar and hold it against movement with the 85 feeder-off carriage 175, said carriage continuing in its movement, and thereby causing relative movement between the carriage and rack-bar, which will force the rollers 193 out of the recesses 197 and into engagement with 90 the straight faces of the rack-bar, causing the rods or bars 178 to be forced downwardly and elevating the feeder-off blocks from the 95 surface of the paper.

In addition to the automatic control of the 100 feeding-off fingers, as just explained, the movement of the carriage will bring the ends of the rack-bar 194 into engagement with suitable stops at the limit of the forward and backward movements to insure the proper position of the feed-fingers for their backward and forward movements, respectively. The angle-bar 5 constitutes the stop for engaging the rack-bar 194 at every rear stroke of the carriage for shifting the rack-bar and throwing the feeding-off fingers into engagement with the pile in readiness for the succeeding forward stroke. Angle-bar 2 engages the rack-bar 194 at the completion of the forward stroke of the carriage unless the rack-bar 110 has been previously engaged and shifted by the automatically-controlled dog 220. The rack-bar is shifted by angle-bar or stop 2 or dog 220 at or before the completion of every forward stroke to insure the lifting of the 115 feed-fingers from the pile preparatory for the succeeding rearward stroke. When the machine is operating properly, the rack-bar will be shifted by the engagement of dog 220 on nearly every forward stroke; but it sometimes 120 happens that a sheet fails to reach registered position before the end of the forward stroke of the carriage, and in this case the dog 220 will not be tripped by the sheet-actuated device, and the rack-bar will therefore be 125 shifted by coming into engagement with angle-bar or stop 2. It will be clear that the rearward movement of the carriage (with rack-bar 194 shifted as shown in Fig. 9) will draw 130

the rack-bar beneath the dog 220 till the dog rests upon the smooth part of the rack-bar, in which position said dog will allow a slight forward movement of the rack-bar 5 upon the carriage when the rack-bar engages the rear stop 5. Fig. 9 of the drawings shows the position of the parts at the completion of a forward stroke, the feed-fingers having been elevated by the operation of dog 220 10 upon the rack-bar.

To further obviate the possibility of two sheets being fed forward from the pile, I arrange two sets of sheet-separators at the forward or delivery end of the machine, each set 15 of separators comprising a lower retarding-bed 244, supported in a casting 243, disposed in front of the delivery end of the machine in the plane of feeding, and an upper vertically-movable horizontally-reciprocating friction pad or block 260. The retarding-bed 244 is preferably formed of hard rubber; but it 20 may be formed of other suitable hard material, and in separating some qualities of paper it may be advisable to apply to the top 25 of the bed a sheet of sandpaper or emery-paper or other similar rough-surfaced material which will present sufficient friction to prevent the forward movement of a sheet of paper which may have followed the top sheet in 30 its forward movement from the pile.

Bolted to the opposite faces of the sliding brackets 171 and 172 is a track-bar 261, which supports the horizontally-reciprocating carriage 262, which carries the friction-pad 260. 35 The carriage 262 is formed with integral lugs 263, which embrace the track-bar 261 and confine the carriage thereon.

264 is a wear-plate supported by adjustable screws 265 between the upper face of the 40 track-bar 261 and the inner face of the integral flange 263 of the carriage. This plate 264 takes up the wear of the carriage, and by means of the screws 265 the freedom of motion of the carriage can be properly regulated. 45 266 is an integral head depending from the carriage 262 and formed with guide-lugs 267, forming a slide in which is supported a vertically-movable bar 268, having a lower forwardly-projecting right-angled extension 269. 50 The forward end of the extension 269 is pivoted between the integral lugs 270 of the upper separator-block or friction-pad 260 upon a pivot-bolt 271.

272 is an integral lug projecting up from 55 the back of the separator-block 260, formed with a vertical slot 273, through which passes an adjustable screw 274, which is seated in a suitably-threaded opening in the extension or arm 269. By means of the pivotal connection at 271 and the adjustable connection at 274 the upper separator-block 260 can be adjusted upon the arm 269.

275 is an integral lug depending from carriage 262, in which is journaled a rock-shaft 60 276, having secured to one end a rock-arm 277, which projects forwardly from the rock-shaft and is provided with a longitudinal slot

70 278, which engages a pin 279 on the vertically-movable sliding bar 268 of the separator. 280 is a rock-arm mounted upon the opposite end of the rock-shaft 276 and adjustably secured thereto by means of a set-screw 281.

282 is a pitman or connecting-link pivoted at its forward end to the upper end of the rock-arm 280 and at its rear end to the lower 75 end of the driving-lever 283, which is pivotally supported at 284 to the end of the bracket-arm 285, formed integral with and projecting from the adjustably-mounted casting 205. The bracket arm or horn 285 is of the same 80 shape as the bracket arm or horn 204, both of said arms being supported upon or formed integral with the same casting 205.

286 is a driving-rod pivoted at 287 to a lever 283 and formed at its forward end with a 85 guiding-loop 288, which embraces the power-shaft 115 and has antifriction-rollers 290 and 291 journaled upon it at the opposite ends of the guide-loop.

292 is a cam for imparting an intermittent 90 oscillatory motion to the driving-lever 283.

308 is a guide-rod pivoted at its forward end to the driving-lever 283 and sliding in a bracket 309, secured to bracket 205.

310 is a spiral spring surrounding rod 308 95 and confined between bracket 309 and an adjustable collar 311, the purpose of the spring 310 being to hold the parts in proper normal position to cause the antifriction-rollers to operate properly upon the cam.

295 are integral lugs projecting from the sliding carriage 262, and 296 are adjusting-screws seated in threaded openings in said lugs 295 and provided with clamp-nuts 297. It will be observed that the inner projecting 105 ends of screws 296 are adapted to engage the opposite edges of the crank-arm 280, said screws being properly adjusted to allow sufficient movement of the rock-arm and rock-shaft to throw the upper separator-block 260 down 110 upon the surface of the paper. This action of lowering or elevating the upper separator-block precedes the movement of the separator-carriage either forward or backward and is caused by the engagement of the rock-arm 115 280 with one of the screws 296.

315 is a pin projecting from the inner face of carriage 262 through a longitudinal slot 261^a of the track-bar 261.

316 is a brake-block supported upon the pin 120 315, and 317 is a spiral spring confined upon pin 316 to cause it to have the proper frictional engagement with the side of the track-bar to resist the initial tendency of the carriage to move forward or backward upon the 125 movement of the driving-lever 283 for the purpose of giving time for the operation of the rock-arm 280, rock-shaft 276, rock-arm 277, and sliding bar 268 in throwing the upper 130 separator-block 260 down upon or elevating it from the surface of the paper.

It will be observed from the drawings that each set of feeding-off devices is arranged behind and adjacent to one set of separators in

order that the separator will be in the best position to take the sheet from the feeding-off devices. This relative position between the feeding-off devices and separators should always be the same, and yet it is essential to provide means for adjusting said devices transversely upon the machine to suit the varying requirements of the machine in handling different-sized sheets of paper. To facilitate said adjustment without interfering with the proper relation of the devices, I have arranged the devices in groups which are adjustable as a whole, as will now be explained.

As already described, the track-bars 170 and 261 are both supported from the sliding brackets 171 and 172, which are respectively mounted upon the angle frame-bars 2 and 5. The bracket-arms 204 and 285, carrying the operating devices of the feeding-off and separator mechanisms, are formed integral with the sliding bracket or casting 205. The bracket 171 has an integral portion 171^a projecting rearwardly from it which is bolted or otherwise rigidly secured to the forward vertical face of casting 205, thus causing the brackets 171, 172, and 205 to move as a single structure transversely of the machine. Referring to Fig. 13, it will be observed that the main driving-shaft 115 is formed with a spline-groove 115^a, extending from end to end. 300 is a sleeve formed with reduced ends and bored longitudinally to fit loosely upon the shaft 115. 301 is a feather-key formed integral with the sleeve 300 and engaging the spline-groove 115^a of the power-shaft. 302 are annular flanges forming an annular groove between them, with which engages a semicircular fin or flange 303^a of the plate 303, projecting up from and formed integral with the casting 171 171^a. The cams 209 and 292 are adjustably keyed to the reduced ends of sleeve 300, while the loop-guide ends 208 and 288 of the driving-rods 206 and 286 respectively embrace the reduced portions of the sleeve 300 and are confined against sidewise motion thereon between their cams and the adjustable collars 304, which are secured to the reduced end of sleeve 300. The bracket or casting 205 has bolts 305 extending through it and engaging in longitudinal slots 306, formed in the channel-bar 3 of the frame. It will therefore be observed that by loosening the bolts 305 the whole set or group of feeding-off devices, separating devices, and their operating mechanisms can be adjusted as a single structure transversely of the machine.

I will now describe the automatically-controlled governor, which arrests the movement of the machine in case more than the maximum number of sheets have been fed forward by the devices above described.

Loosely journaled upon the outer end of the main driving-shaft 115 is a large power-gear 320, which has secured to it or formed integral with it a clutch-disk 321, having a radial notch 322. Keyed to the outer end of the shaft 115, adjacent to the clutch-disk 321, is

a similar disk 323, secured by means of a key 324 and formed with a radial notch 325. Pivoted upon a pin 326, supported in the lug 326^a, 70 projecting from and formed integral with the aforesaid clutch-disk 323, is a clutch-dog 327, having an engaging tooth 328, which is adapted to engage in the radial notches 322 and 325 of the clutch-disks when said notches register or correspond in position.

329 is a pin projecting from one side of the dog 327, and 330 is a rod pivoted to pin 329 and projecting through a guide-lug 331, projecting from the disk 323. 80

332 is a spiral spring confined upon the rod 330, between the lug 331 and collar 333, for holding the dog 327 against the peripheries of the clutch-disks and forcing the tooth 328 into the notches 322 325, when they assume 85 proper position.

334 is a head or enlarged lug formed integral with the clutch-disk 323.

336 is a heel portion formed integral with the clutch-dog 327, said heel portion projecting over the enlarged lug or head 334 into the plane of the disk 323 for engaging it to arrest the motion of the machine. 90

337 is a bracket secured to the side frame-bar 1, and 338 is a pin supported upon said bracket. 95

339 is a sliding head having having two arms 339^a and 339^b projecting from it and sliding upon pin 338 and provided with a guide-strap 340 on the arm 339^a, which embraces a guide-pin 341, projecting from the main frame. 100

342 is a rock-shaft journaled in bearings 343 of the main frame, and 344 is a rock-arm secured to one end of the shaft 342 by means of set-screw 345. The lower end of the rock-arm 344 is forked or bifurcated at 346 to engage the arm 339^b of the sliding head 339. 105

347 is an arm keyed to shaft 342, and 348 is a pin mounted in the outer end of the arm 110 347 and extending parallel to the shaft 342.

349 is a head loosely journaled upon shaft 342, between the arm 347 and the collar 350.

351 is an arm projecting from head 349 and carrying a weight 352 at its outer end. 115

353 is a heel or shoulder formed upon the head 349, and 354 is an armature mounted at one end upon a lever 355, pivoted upon bracket 356 and provided at its other end with a hook or dog 357, which engages with 120 the heel or shoulder 353 of the loosely-journaled head 349.

358 is a spiral spring surrounding a rod 359, projecting up from the armature-lever 355 through an arm 360, supported from the main 125 frame. The spiral spring 358 is confined between the armature-lever 355 and bracket 360 for holding the dog 357 into engagement with heel or shoulder 353.

361 is an electromagnet supported upon 130 bracket 362 in position to attract the armature 354 when an electric current passes through it.

Operating in conjunction with the clutch

mechanism just described I provide an electric contact device adapted to be operated by more than the maximum number of sheets for closing the circuit and dropping the 5 weighted arm 351 to throw it into engagement with the pin 348 to cause the shifting of the sliding head 339, which will throw the arm 339^a into the path of the heel 336 of dog 327, disengaging the tooth 328 from the rotary 10 notches 322 and 325 and allowing the power-gear 320 to rotate and arrest the driving-shaft of the machine by the engagement of said arm 339^a with the head or dog 334. This paper-operated electric contact device is supported 15 adjacent to the central line of the machine at the delivery end and is clearly illustrated in Figs. 14 and 14^a of the drawings. Depending from the forward angle frame-bar 2 of the machine is an arm 365, having a forwardly-projecting lower bent end 366. Pivoted beneath the bent end 366 is a lever 367, pivoted upon screws 368, seated in bracket 369. 20

370 is a spiral spring supported upon a pin 371 between the forward end of lever 367 and 25 the bottom plate of bracket 369 for holding the forward end of lever 367 in close proximity to the bent end 366 of arm 365.

372 is an adjustable stop for regulating the proximity of the lever 367 to the end 366 of 30 arm 365.

373 is a bracket carrying one of the contact-pins, from which extends the circuit-wire 374. The other circuit-wire 375 leads from the lever 367 and passes to the electromagnet 361, 35 and from there to one of the main-circuit wires 247. The wire 374 is connected with the other main-circuit wire 248. When more than the maximum number of sheets are forced between the lever 367 and forward bent 40 end of arm 365 by the feeding instrument, the lever will be moved sufficiently far on its pivot by the pressure of the several thicknesses of paper to make contact at point 373, which will energize the magnet 361 and release the automatic weighted arm 351, which 45 in turn disengages the clutch and arrests the operation of the machine, as already explained.

450 are adjustable brackets provided with 50 set-screws 451 and mounted upon the frame-bar 452 at the delivery end of the machine.

453 are rods having rear beveled ends 454 and secured to the brackets 450. A number of rods 453 are supported upon the bar 452 55 in the plane of the paper being fed off, their purpose being to support the paper after it passes from the drop-rollers.

455 is a bar supported above the plane of the paper, and 456 are adjustable brackets 60 carrying rods 457, which have their rear ends 457^a upturned, as shown.

458 are set-screws in the brackets for holding them in any desired adjusted position on the bar 455. The rods 453 and 457 confine 65 the sheets of paper below and above and prevent the air-blasts from blowing them out of their proper path.

It will be observed that the clutch mechanism just described is located at the forward right-hand corner of the machine. The main driving-shaft 115 extends across the machine and is provided with suitable mechanism, such as shown in Fig. 16, for conveying motion to the several parts of the machine. Keyed to the outer end of the main shaft 115 70 is a worm cog-gear 380, which meshes with a similar worm-gear 381, keyed to the shaft 382, extending longitudinally of the machine and supported in bearings 383 and 384.

385 is a bevel-gear adjustably splined to 80 shaft 382, and 386 is a bevel-gear meshing therewith and keyed to the end of the buckler-operating cam-shaft 29.

387 is a bracket-bearing supported upon shafts 29 and 382 and sliding upon shaft 382 85 for confining the bevel-gears 385 and 386 in proper position and causing gear 385 to be adjusted on its shaft by the movement of the heads 25, shaft 29, and bar 27, which support the bucklers. By this means the buckler-operating mechanism is driven.

Inside of the gear 380 a sprocket-gear 390 is keyed to the power-shaft 115, a sprocket-chain 391 leading from said sprocket-gear to a similar sprocket-gear 392 on a stationary 95 journal 393, supported from the side frame.

395 is a stationary shaft supported in the side frame of the machine and projecting upon both sides of the side frame.

396 is cog-gear loosely journaled upon the 100 outer end of shaft 395 and receiving motion from the sprocket 392 through large gear 394. This gearing is shown in Figs. 16 and 16^a. The sprocket-wheel 392^a is a tension-guide for sprocket-chain 391.

397 are rock-arms loosely journaled concentric to gear 396 upon the stationary journal-shaft 395 and upon a similar bearing (not shown) at the opposite side of the machine. Journaled in the forward bearings 399 of rock-arms 397 is the drop-roller shaft 400, having a gear 401 at one end meshing with gear 396 and carrying the drop-rollers 402, which operate with the lower feed-rollers 403. The feed-rollers 403 are journaled upon bearings 115 which support their upper surfaces in the horizontal plane of feeding.

404 are rock-arms loosely journaled upon the bearings 395 and having antifriction-rollers 405 at their upper ends, which run upon the peripheries of cams 406, keyed to the main shaft 115, inside of the main bearings 115^a of the main frame.

397^b is a head or box formed integral with each of the hub portions 397^a of rock-arms 125 397. The heads 397^b have integral lugs 407, in which are seated the adjusting-screws 408, which bear upon the opposite edges of rock-arms 404 for adjusting the relative position of rock-arms 404 to rock-arms 397.

In the ordinary operation of the machine cams 406 normally support the drop-rollers 402 above the feed-rollers 405 and allow them to drop at intervals to catch the forward edge

of the sheet of paper and feed it off from the machine. To prevent the momentum of the drop-rollers feeding a sheet from the machine after the clutch has been automatically thrown out and during the moment just before the machine is brought to a full stop, I provide the rock-arms 410, journaled upon brackets 411 and each carrying a lug 412, which is adapted to engage a similar lug 413 upon bracket-arms 397 for supporting the drop-rollers in elevated position. The rock-arms 410 are connected through rods 415 with the rock-arms 416, keyed to a shaft 417, which shaft is journaled in bearings 418 and has bevel-gear connections 419 420 with the shaft 342, so that the movement of said shaft 342 for operating the clutch will move rock-arms 410 for holding the drop-rollers in elevated position. For the purpose of enabling the throwing out of the machine by hand I provide the rock-shaft 417 with hand-levers 417^a.

In the brackets 425 are seated the adjustable set-screws 426, having clamp-nuts 427, which screws are adapted to engage the journal ends 399 of rock-arms 397 for regulating their downward movement.

In Fig. 17 I have represented my improved device for gearing the feeding-machine to a folder. 430 is the frame of the folding-machine. 431 is a bar having a dovetailed or **T** groove 431^a formed in one face, which bar is journaled upon the main driving-shaft 115 and is provided with a bolt 432, which operates in the segmental groove 433, formed in the plate 434, which is also formed integral with the bearing 115^a, the segmental groove 433 being concentric with shaft 115. The dovetailed or **T** groove 431^a is adapted to receive the journal-bolts 431^b, formed with **T**-heads and upon which the gears 435 436 are journaled. The gear 435 is in mesh with the main driving-gear 320. By loosening the nut of bolt 432 it will be observed that the slotted bar 431 can be shifted to any angle to suit the height of the driving-gear of the folder or other machine to which the feeder is geared, and by properly arranging the gears supported in said slotted bar the folder can be driven at any desired relative speed.

The operation of my improved machine as a whole is substantially as follows: The rear corners of the top sheet of the pile are first buckled by the operation of the buckling devices, the pressure upon the holding-down fingers being released while the corners are being buckled and being applied immediately after the corners of the sheet have been withdrawn from under them. As soon as the corners of the sheet have been buckled the air-blasts blow currents of air under the sheet from the rear and sides. The feeding-off devices then come into play to engage the sheet and move it from the pile, the friction brake-blocks resting on the top sheet and the exposed rear edges of the subadjacent sheets to assist in holding back the under sheets in cases where more than one sheet has been

started by the bucklers and air-blasts. The holding-down blocks or shoes engage the pile just after the rear edge of the top sheet being fed off passes from beneath them to further assist in separating any under sheets which may have been moved and to further assist in keeping the pile intact. When the feeding-off fingers start on their forward movement, the rack-bar which controls them is in normal position, with the curved notches in engagement with the small rollers carried by the bars which control the feed-fingers. As soon as the forward edge of the sheet reaches the electric contact devices the electric circuits are broken and the pawls or dogs are dropped down into engagement with the teeth of the rack-bars, holding said rack-bars against further movement, while the feeder-off carriages continue to the end of their stroke, thus causing the elevation of the feed-fingers from the paper. Each set of feeding-off devices is independently controlled by the electric-contact-controlling device directly in front of it, and the sheet is thereby squared and registered at its front edge. The feeding-off fingers will be held in elevated position until the end of the return stroke, when the rack-bars will be engaged by a suitable stop, the angle-bar 5 for shifting them into normal position allowing the feed-fingers to again drop upon the surface of the paper. If two or more sheets have been fed forward to the separator, the circuits controlling the electromagnets will continue to be broken by the interposition of the sheets, allowing the dogs to remain in engagement with the rack-bars, and thus causing the feed-fingers to be immediately lifted when the carriages again start forward, and preventing the feed of another sheet until the previous sheets have passed the separators. In case no sheet has been fed forward by the feeding-off devices to operate the electric contact devices the rack-bars will engage the stops at the front of their stroke, causing them to shift and elevate the feeding-off fingers from the paper for the rearward stroke of the carriages. The feeding-off devices deliver the front marginal edge of the top sheet of paper part way onto the rear portions of the retarding-beds 244, in which position the movements of the feeding-off devices are arrested by the electric-contact-controlling devices. While the sheet is assuming this position, the reciprocating friction pads or blocks 260 are moving to their rearmost elevated position, and immediately after the feeding-off devices are elevated from the paper the said friction-pads descend upon the aforesaid front marginal part of the advanced top sheet and obtain a frictional hold upon the sheet and move forward, pushing said sheet over the retarding-bed, and thereby separating any under sheets which may have adhered, delivering said top sheet to the drop-rollers, which feed it out of the feeding-machine to the folder or other machine designed to receive the sheet. It sometimes happens

that the feeding-off fingers advance two or more sheets simultaneously from the pile to the separators. Under these circumstances the portions of the sheets which have become 5 interposed between the top sheets (engaged by the movable friction-pads) and the retard-ing-beds are prevented from further following the top sheet by the friction between the beds and said under sheets, which is greater 10 than the friction between the several sheets. Hence my separators effectually prevent the feeding-machine from delivering more than one sheet at a time.

During the operation of the several feeding 15 devices the height of the pile of paper is automatically regulated by the governor, as described, and the operation of the whole mechanism automatically arrested when the operations are not perfect or by hand when it is 20 desired to stop the feeding operation.

I am aware that it has been proposed to construct paper-feeding machines with a lower stationary separator-plate and an upper movable separator friction pad or block, which in 25 addition to separating the top sheet from the next underlying sheet or sheets serves to feed the sheets off from the pile of paper, and I am also aware that it is old to provide a paper-feeding machine with feeding instruments 30 and sheet-delivery devices which take the sheets from the feeding instruments and feed them from the machine; but I am not aware that it has ever been proposed to provide a machine with sheet-separators at the delivery 35 end of the machine, in combination with independent feeding instruments which start the sheet from the pile and deliver its front edge to the separator, the separator operating alternately with the feeding instruments and 40 imparting a secondary forward impulse to the sheet to separate it from the underlying sheets and deliver it singly to the delivery mechanism, nor am I aware that it has ever been proposed to combine with such machines buckling 45 devices or preliminary separating devices for separating the top sheet at the rear before it is started from the machine by the feeding instruments. Such combinations I claim to be broadly new in my present application. The results of such combinations are 50 vastly superior to the results of all other machines, the chief advantage lying in the fact that the independent feeding instruments engage the sheets to the rear of their forward 55 edges (leaving the forward edges free to move over the separator-bed) and never fail to push the forward marginal edge of the top sheet onto the lower separator retarding-bed in position to be subsequently taken hold of by the upper 60 movable friction-pads of the separators, while in all other machines employing a lower separator-bed and upper separator-block the movable separator-block also feeds the paper from the pile to the retarding-bed and the 65 forward edges of the sheets are constantly crowded against the edge of the lower separator-bed (on account of the necessary down-

ward pressure of the blocks upon the extreme forward edge of the sheets when the sheet is started from the pile) and tend to curl or 70 bend downwardly under the action of the upper movable separator-blocks and very frequently catch against the separator-bed and cause the rumpling up and destruction of the sheets and sometimes even the breaking 75 of the machine if the operation is not quickly arrested.

By the expression used in the claims "feeding devices having a normally active frictional engagement with the sheets on their 80 forward stroke" I mean to cover such feeding instruments which take a positive frictional hold upon the surface of the top sheet of the pile on their forward stroke to cause the single sheet to move positively forward 85 with the feeding instruments the whole distance of their stroke while in engagement as distinguished from combing devices which do not have a positive frictional hold on the sheets, but slip or slide over the surface of 90 the top sheet and move a number of sheets. I do not claim such automatically-controlled frictional feeding instruments in my present application, except in combination with alternately-operating sheet-separators and other 95 devices; but in my copending application filed June 12, 1896, Serial No. 595,373, I claim, broadly, such true frictional feeding instruments, in combination with means operated by the sheets of paper, for automatically controlling their operation. I also claim in the same case said automatically-controlled true frictional feeding instruments in combination with sheet-separating means and the broad combination of sheet-buckling devices, means 100 for advancing a sheet, and upper and lower separators for separating the advanced sheet from any chance underlying sheets. In said application, Serial No. 595,373, I have further claimed the combination of a sheet-retarding 105 bed at the delivery end of the machine, a feeding-pad operating upon the top of the front portion of the pile of sheets and over said retarding-bed to carry the top sheet onto said bed and separate it from any underlying 110 sheets which may have been fed with it, an auxiliary feeding-pad operating upon the pile at the rear of the front feeding-pad to assist the travel of the sheets, and sheet-delivery 115 mechanism to convey the advanced separated sheet from the machine. The two feeding and separating pads in said application operate simultaneously under the control of an automatic device. The feeding and separating instruments of my present case operate 120 upon a radically-different principle in that the forward friction-pad operates solely as a separator-pad and does not come in contact with the pile, but engages the sheet only after it has been fed upon the retarding separator-bed by the feeding-off instruments operating 125 in rear of it upon the pile, and, further, the feeding-off instruments operating upon the pile are operated and controlled in- 130

dependently of the separator-pad for moving the sheet onto the retarding separator-bed and registering its position thereon before the separator-pad comes into operation upon the sheet. My claims on the feeding and separating features of the present machine are therefore distinguished from the structure covered by said application, Serial No. 595,373, by these important particulars—viz., that the feeding-off and separating instruments in the present case operate independently, and they come into play successively or alternately. In this connection I would have it understood that by the expression "alternate action of the feeding and separating devices" used in the specification and claims of my present case I mean said devices are brought into operative engagement with a sheet successively in order that the sheet may be pushed forward onto the retarding-bed by the feeding devices before it is engaged by the separating devices, and the term "alternately" used in this connection in the claims is intended to cover the successive engagements of the sheet by said devices whether the feeding devices disengage the sheet when the separating devices take it or continue in operation during a part or the remainder of their stroke after the separator has come into play.

The structure of the sheet-feeding instruments described and illustrated, but not claimed in my present application except in combination with sheet-separators, is also subject to the claims in an application filed by me July 13, 1894, Serial No. 517,396, for improvements in paper-feeding machines, in which application I have claimed, broadly, the combination of means for moving the top sheet of a pile, mechanism for operating the sheet-moving means, a tripper suspended in the path of the top sheet and adapted to be operated thereby, a rack carried by the sheet-moving means, and a device controlled by the tripper adapted to engage the rack and arrest the operation of the sheet-moving means.

I do not claim, broadly, means for automatically throwing the machine out of gear and arresting its operation under control of a device operated by the passage of a greater number of sheets than can be properly taken care of by the machine, as such a mechanism is disclosed in my patents granted September 8, 1896, Nos. 567,302 and 567,303; but I do claim the novel combinations of elements herein disclosed for producing such a result.

In another application, originally filed by me September 16, 1896, renewed October 16, 1897, (renewal Serial No. 655,480,) for improvements in paper-feeding machines I have illustrated and described, but have not claimed, the independently-controlled feeding-off fingers in combination with the separator-beds at the delivery end of the machine and the separator-pads operating alternately with the feeding-off fingers and engaging the sheets above the separator-beds only for separating them from any chance underlying

sheets, this structure being covered, broadly, in my present application, as above explained.

In the various other combination claims I would have it understood that I do not wish to limit myself to the specific structures of the several devices except when specifically included in the claims.

Having thus described my invention, what I claim, and desire to secure by Letters Patent, is—

1. In a paper-feeding machine, the combination of a paper-supporting table, and devices for feeding sheets of paper therefrom, with a sheet-buckling device comprising a reciprocating carriage, a spring-pressed buckling-finger journaled upon the carriage, a rock-arm also journaled upon the carriage and engaging the buckling-finger, a stop-lug on the carriage limiting the movement of the rock-arm, and an operating-lever connected with the rock-arm, substantially as set forth.

2. In combination with a paper-feeding machine, a sheet-buckling device comprising a reciprocating carriage, a guideway or track on which the carriage reciprocates, a spring-pressed buckling-finger journaled upon the carriage, a rock-arm also journaled upon the carriage and engaging the buckling-finger, a stop-lug on the carriage limiting the movement of the rock-arm, an operating-lever connected with the rock-arm and adapted to move it on its journal for raising and lowering the buckling-finger and throwing the rock-arm into engagement with the stop, and a friction-brake upon the carriage engaging the way or track for arresting the initial tendency of the carriage to move to give the buckling-finger time to move, substantially as set forth.

3. In combination with a paper-feeding machine, a sheet-buckling device comprising a reciprocating carriage, a guideway or track on which the carriage reciprocates, a pin projecting from the carriage, a brake-block loosely supported upon said pin in engagement with the way or track, a spring confined upon said pin in engagement with the brake-block, a sheet-buckling finger journaled upon the carriage, a rock-arm also journaled upon the carriage and engaging the buckling-finger, a stop upon the carriage with which the rock-arm engages, and an operating-lever connected with the rock-arm, substantially as set forth.

4. In combination with a paper-feeding machine, a sheet-buckling device comprising a sliding plate or carriage, a supporting-frame having guide-flanges forming a guideway or track in which the plate or carriage reciprocates, a pin projecting from the plate or carriage through an elongated slot of said supporting-frame, a brake-block loosely supported upon said pin in engagement with the face of the supporting-frame, a spiral spring confined upon said pin in engagement with the brake-block, a journal-pin projecting from the plate or carriage, a bell-crank rock-arm or lever loosely journaled upon said pin, a

- sheet-buckling finger loosely journaled upon said pin alongside the rock-arm, a spring confined upon said pin and engaging the pin at one end and the buckling-finger at the other end, an extension of the rock-arm projecting beneath the buckling-finger, a stop on the carriage with which the rock-arm engages, an operating-lever connected with the rock-arm, and a cam engaging said operating-lever, substantially as set forth.
5. In combination with a paper-feeding machine, a sheet-buckling device comprising a suitable supporting-frame, a vertically-movable spring-pressed holding-down finger supported in the frame, a vertically-movable head engaging the spring of the holding-down finger and free to move independently of said finger, an operating-lever connected with the head adapted to operate it for removing the pressure of the spring from the holding-down finger without elevating said finger, a reciprocating spring-pressed buckling-finger, and means for reciprocating the buckling-finger, substantially as set forth.
10. In combination with a paper-feeding machine, a sheet-buckling device comprising a suitable supporting-frame, the spring-pressed holding-down finger, a rocking lever journaled in the frame, a cam-shaft, a cam on said shaft engaging said rocking lever, a head connected with said lever and engaging the spring of the holding-down finger, a reciprocating carriage sliding in the supporting-frame, a spring-pressed buckling-finger journaled upon said carriage, a rock-arm also journaled upon the carriage and engaging the buckling-finger, a stop on the carriage, an operating-lever connected with the rock-arm, and a cam on said cam-shaft engaging said operating-lever, substantially as set forth.
15. In combination with a paper-feeding machine, the combination of a paper-supporting table, suitable feeding-off devices, a supporting-bar above the table, a bracket adjustably mounted upon the supporting-bar, a rock-arm journaled in said bracket, a rubber-faced resistance-block mounted upon said rock-arm, and a suitable spring for forcing the rock-arm downwardly and holding the resistance-block constantly upon the surface of the paper, substantially as set forth.
20. In a paper-feeding machine, the combination of a paper-supporting table, suitable feeding-off devices, and a paper-holding device comprising a supporting-bar and a rotary shaft above the paper-table, a bracket adjustably mounted upon the bar, a vertically-movable rod supported in a suitable bearing in said bracket, the holding-down shoe or block adjustably mounted upon said rod, a spring for forcing the rod and shoe downwardly, a cam on the shaft, a bracket journaled upon the shaft upon opposite sides of the cam, said shaft-bracket being secured to the bracket on the bar, a lever pivoted to the shaft-bracket and engaged by the cam, and a

tappet on the rod engaged by the lever, as set forth.

9. In a paper-feeding machine, the combination of a paper-supporting table, a suitable supporting-frame, feeding-off devices, the track-bars 13, heads 25 sliding upon bars 13, the bar 27 connecting heads 25, shaft 29 journaled in heads 25, suitable means for rotating shaft 29, means for adjusting the heads 25 simultaneously longitudinally of the machine, and the buckling devices, retarding-brakes, and paper-holding devices supported upon said bar 27, whereby all of said devices can be adjusted as a single structure, substantially as set forth.

10. In a paper-feeding machine, the combination of a paper-supporting table, suitable feeding-off devices, a rotary table-elevating shaft provided with a driving-ratchet, an arm carrying a pawl adapted to operate the ratchet, a hood or shield embracing a segment of the ratchet and adapted to hold the pawl out of engagement therewith, a suitable device controlled by the height of the pile of paper for holding the hood or shield in position to disengage the pawl from the ratchet, and automatic mechanism engaging the hood or shield and adapted to automatically move the shield for uncovering the ratchet, when the shield is released by said device, to allow the operation of the pawl, substantially as set forth.

11. In a paper-feeding machine, the combination of a paper-supporting table, suitable feeding-off devices, a rotary table-elevating shaft provided with a driving-ratchet, an arm carrying a pawl adapted to operate the ratchet, an oscillatory hood or shield embracing a segment of the ratchet and adapted to hold the pawl out of engagement therewith, a suitable device engaging the hood or shield and giving it a normal tendency to uncover the ratchet to the action of the pawl, suitable means for moving said hood or shield against its normal tendency, throwing it into position to disengage the pawl from the ratchet, and a device controlled by the height of the pile of paper for holding the hood or shield in position to keep the pawl out of engagement with the ratchet, substantially as set forth.

12. In a paper-feeding machine, the combination of a paper-supporting table, suitable feeding-off devices, a table-elevating shaft having a ratchet-wheel, a suitably-supported operating-pawl adapted to intermittently engage and rotate the ratchet-wheel, an oscillatory hood or shield embracing a segment of the ratchet-wheel, a vertically-movable rod connected with the hood or shield, and a pivoted dog controlled by the varying height of the pile of paper and adapted to engage the rod for holding it in elevated position, and the hood or shield in position to hold the pawl out of engagement with the ratchet, substantially as set forth.

13. In a paper-feeding machine, the combination of a paper-supporting table, a paper-elevating shaft having a ratchet-wheel, an oscillating pawl adapted to engage said ratchet-wheel, a hood or shield embracing a segment of the ratchet-wheel, a vertically-movable rod connected with the hood or shield, a dog controlled by the height of the pile of paper adapted to hold said rod in elevated position, and means for oscillating the hood or shield and elevating and lowering the rod when the dog is disengaged therefrom, whereby the pawl is allowed to operate till the paper is elevated sufficiently to throw the dog into engagement with the rod, substantially as set forth.

14. In a paper-feeding machine, the combination of a paper-supporting table, suitable feeding-off devices, a table-elevating shaft having a ratchet-wheel, an oscillatory lever carrying an operating-pawl, an oscillatory hood or shield embracing a segment of the ratchet, a vertically-movable rod connected with the hood or shield, and a pivoted lever provided with a dog at one end and a freely-journalled roller at the other end, said dog being adapted to engage the rod for holding it in elevated position when the surface of the pile is at the required height, substantially as set forth.

15. In a paper-feeding machine, the combination of a paper-supporting table, suitable feeding-off devices, a table-elevating shaft having a ratchet-wheel, an oscillatory lever carrying an operating-pawl, an oscillatory hood or shield embracing a segment of the ratchet and adapted to be operated by the pawl-carrying lever, and a device controlled by the height of the pile of paper for holding the hood or shield in position to disengage the pawl from the ratchet, substantially as set forth.

16. In a paper-feeding machine, the combination of a paper-supporting table, suitable feeding-off devices, a table-elevating shaft having a ratchet-wheel, an oscillatory lever carrying an operating-pawl, an oscillatory hood or shield embracing a segment of the ratchet, a suitable spring device engaging the hood or shield and giving it a normal tendency to uncover the ratchet to the action of the pawl, a suitable device operated by the pawl-carrying lever and engaging the hood or shield and adapted to move it against the action of the spring device, into position to disengage the pawl, and a device controlled by the height of the pile of paper for holding the hood or shield in position to disengage the pawl from the ratchet, substantially as set forth.

17. In a paper-feeding machine, the combination of a paper-supporting table, suitable feeding-off devices, the table-elevating shaft provided with a ratchet-wheel, an oscillatory lever supporting a driving-pawl, means for oscillating the said lever, an oscillatory hood or shield embracing a portion of the teeth of

the ratchet-wheel, a vertically-movable rod connected with the hood or shield and formed with a suitable notch or recess, a pivoted bell-crank lever formed with a dog at its upper end and bearing with its lower end against the surface of the pile of paper, said dog adapted to engage in said notch or recess for holding the rod in elevated position and the hood or shield in position to prevent the engagement of the pawl with the ratchet, a rock-shaft having rock-arms at its opposite ends which are connected respectively with the oscillatory hood or shield and the oscillatory pawl-carrying lever through suitable rods, whereby said hood or shield will be oscillated and the vertically-movable rod moved up and down when it is released by the dog, substantially as set forth.

18. In a paper-feeding machine, the combination of a paper-supporting table, suitable feeding-off devices, a table-elevating shaft having a ratchet-wheel, an oscillatory pawl-supporting arm, and a pawl pivoted to said arm, an oscillatory hood or shield embracing a segment of the ratchet, a suitable rock-shaft, a rock-arm upon said shaft connected with the hood or shield through a suitable link, a second rock-arm keyed to the opposite end of said rock-shaft, a rod pivoted to said second rock-arm and extending through a head attached to the lower end of said pawl-carrying lever, a tappet mounted upon said rod and adapted to be engaged by said head, means for operating the pawl-carrying arm, a suitable spring for holding the hood or shield in normal position, and means controlled by the height of the pile of paper for holding the hood or shield in position to prevent the operation of the pawl in which position the tappet on the rod will be out of engagement of the head upon the pawl-carrying arm, substantially as set forth.

19. In a paper-feeding machine, the combination of a paper-supporting table, suitable feeding-off devices, a table-elevating shaft having a ratchet, an oscillatory arm carrying a pawl adapted to operate the ratchet, a cam mounted upon a shaft, an operating-rod connected with the pawl-carrying arm and engaged and driven by the cam, a spring-actuated rod holding the operating-rod in engagement with the cam, an oscillatory hood or shield journalled upon the table-elevating shaft and embracing a segment of the ratchet, a suitable rock-shaft connected with said hood or shield through a rock-arm and rod, a spring-actuated rod engaging the rock-arm and giving the hood or shield a normal tendency to uncover the ratchet to the action of the pawl, a second rock-arm keyed to the rock-shaft and a rod extending therefrom through a head carried by the pawl-carrying arm, a tappet on said rod adapted to be engaged by said head, a vertically-movable gage-rod connected with the hood or shield, and a dog controlled by the height of the pile of paper adapted to engage the gage-rod and hold

it in elevated position, substantially as set forth.

20. In a paper-feeding machine, the combination of a sheet-retarding bed at the delivery end of the machine, a frictional separating-pad operating only upon the sheets of paper over the aforesaid bed to carry the top sheet over said bed, an independent auxiliary feeding-off instrument operating upon a pile 10 of sheets at the rear of the front separating-pad to feed off the top sheet from the pile onto the retarding-bed before said sheet is engaged by the separating-pad, and sheet-delivering mechanisms conveying said advanced sheet 15 from the retarding-bed, substantially as set forth.

21. In a paper-feeding machine, the combination with sheet-buckling mechanism operating upon the top of the pile of sheets for 20 effecting a preliminary separation of the successive sheets, suitable feeding devices advancing the sheets part way from the pile, and sheet separating and propelling devices at the delivery end of the machine operated success- 25 sively to the feeding devices to receive the front margin of the sheet advanced by the feeding devices and impart a secondary forward impulse to said sheet and at the same time separate it from any chance underlying 30 sheet brought forward by the feeding devices, substantially as set forth.

22. In a paper-feeding machine, the combination with sheet-buckling mechanism operating upon the rear portion of the pile of paper 35 to be fed, sheet-retarding beds at the delivery end of the machine, separating-pads operating only upon the front portions of the sheets of paper over the retarding-beds to carry the top sheets over the same, auxiliary feeding- 40 off instruments operating upon the pile of paper at the rear of the aforesaid front pads and independently of said front pads to feed off the top sheets from the pile and onto said beds, and sheet-delivering mechanisms removing 45 said advanced sheet from the retarding-beds, as set forth.

23. In combination with the feeding devices advancing the top sheet part way upon the pile, sheet separating, and propelling devices 50 located at the delivery end of the machine and operated alternately with said feeding devices to receive the front margin of the advanced sheet and impart a secondary forward impulse to said sheet and at the same time 55 separate it from the underlying sheet while the top sheet is liberated from the feeding devices, as set forth.

24. A paper-feeding machine comprising sheet-buckling devices, sheet-feeding devices 60 advancing the buckled sheet part way upon the pile, and sheet separating and propelling devices located at the delivery end of the machine and operating alternately with the said feeding devices to receive the front marginal 65 portion of the advanced sheet and impart a secondary forward impulse to said sheet and simultaneously separate the same from the

underlying sheet while the feeding devices are carried out of contact with the top sheet, as set forth.

25. In a paper-feeding machine, the combination with the paper-feeding instrument advancing the top sheet part way from the pile, of a sheet-separator consisting of a bed disposed in front of the delivery end of said machine to receive upon it the front margin of the top sheet advanced by the aforesaid feeding instrument, and a friction-pad reciprocating over said bed and moving vertically at the ends of its strokes to press the advanced 80 marginal portion of the top sheet upon the bed during the forward motion of the pad, and thereby impart a secondary advancing impulse to the top sheet and separating the same from the underlying sheet, as set forth. 85

26. In a paper-feeding machine, the combination of a sheet-retarding bed at the delivery end of the machine, the frictional separating-pad operating upon the sheets of paper over said retarding-bed to carry the top 90 sheet over said bed and separate it from any underlying sheets, an independent auxiliary frictional feeding-off instrument operating upon a pile of sheets in rear of the retarding-bed and separating-pad to engage and feed 95 off the top sheet from the pile onto said retarding-bed before said sheet is engaged by the separating-pad, and an automatic controlling device actuated by the sheet fed off and adapted to render the feeding instrument 100 inactive when the sheet reaches registered position on the retarding-bed, substantially as set forth.

27. In a paper-feeding machine, the combination of a sheet-retarding bed at the delivery end of the machine, the frictional separating-pad operating upon the sheets of paper over said retarding-bed to carry the top sheet over said bed and separate it from any underlying sheets, two independent frictional 110 feeding-off instruments arranged transversely of the line of feed and operating upon a pile of sheets in rear of the retarding-bed and separating-pad to engage and feed off the top sheet from the pile onto said retarding-bed before said sheet is engaged by the separating-pad, and two independent automatic controlling devices arranged transversely of the line of feed and actuated by the sheets fed off and operatively connected 120 with the respective independent feeding instruments for rendering them inactive independently as the part of the sheet in front of each instrument reaches registered position, whereby the successive sheets are accurately 115 squared, registered and fed singly from the machine, substantially as set forth.

28. In a paper-feeding machine, the combination of a paper-feeding instrument advancing the sheet part way from the pile, and a 130 sheet-separator consisting of a bed disposed in front of the delivery end of the machine and in a plane to receive the front marginal portion of the sheet advanced by said feed-

ing instrument, a guide parallel with said bed, a friction-pad supported movable longitudinally on said guide, and operating alternately or successively to the feeding instrument, and mechanism imparting to said pad a reciprocating motion combined with a vertical motion to and from the bed respectively at the rear and front ends of its strokes, as set forth.

29. In a paper-feeding machine, the combination with the feeding instruments advancing the top sheet from the pile, of beds in front of the delivery end of said machine and disposed to receive upon them the front marginal portion of the advanced sheet, longitudinal guides parallel with said beds, slides riding on said guides, levers pivoted to the slides, friction-pads connected to said levers and carried thereby vertically to and from the aforesaid beds, stops on the slides limiting the oscillations of the levers and causing the same to impart reciprocating motion to the slides, and mechanism transmitting motion to the said levers, as set forth.

30. In a paper-feeding machine, the combination of suitable feeding devices arranged to advance the top sheet part way from a pile of paper, with sheet separating and propelling devices disposed at the delivery end of the machine and adapted to receive the front margin of the sheet from said feeding devices and impart a secondary forward impulse to it and at the same time separate it from any underlying sheet or sheets, means for automatically controlling the feeding devices to arrest their action before the separating and propelling devices come into play, and suitable means for feeding the sheet out of the machine, substantially as set forth.

31. In combination with the independently operating feeding-off instruments, a sheet-buckling device over the rear portion of the pile of paper, a sheet-separating bed at the delivery end of the machine, a reciprocating frictional separating-pad operating above said bed, sheet-supporting rollers at said end of the machine, drop-rollers over said supporting-rollers, and mechanisms imparting rotary motion to said drop-rollers, and intermittently elevating and dropping them, as set forth.

32. In a paper-feeding machine, the combination of a paper-supporting table, with feeding-off devices comprising a reciprocating carriage, driving mechanism connected with the carriage, suitable feeding instruments pivotally mounted upon the carriage, one to the rear of the other, and an automatically-controlled bar mounted upon the carriage and movable with relation to the carriage and feeding instruments and adapted to move the feeding instruments out of operative relation with the top sheet of the pile, substantially as set forth.

33. In a paper-feeding machine, the combination of a paper-supporting table, with feeding-off devices comprising a reciprocating carriage, a suitable feeding instrument movably

mounted upon the carriage, an automatically-controlled bar movably mounted in said carriage and formed with a cam-face, a part connected with the feeding instrument and engaged by the cam-face of the bar, and means thrown into operation by the movement of a sheet from the machine for changing the relative position of the bar and feeding instrument to cause said bar to throw the feeding instrument out of operation, substantially as set forth.

34. In a paper-feeding machine, the combination of a paper-supporting table, with feeding-off devices comprising a reciprocating carriage, suitable feeding-fingers pivoted to said carriage, a rack-bar mounted on said carriage and movable with relation to the feeding-fingers and adapted to raise the feeding-fingers, a pawl upon a stationary support adapted to engage the rack-bar, and means operated by the sheet being fed off adapted to throw the pawl into engagement with the rack-bar, substantially as set forth.

35. In a paper-feeding machine, the combination of a paper-supporting table, with feeding-off devices comprising a reciprocating carriage, spring-pressed feeding-fingers pivoted to said carriage, vertically-movable bars or rods engaging the feeding-fingers, a bar movably supported in the carriage in engagement with the vertically-movable bars or rods and formed with recesses into which said bars or rods project, and means for changing and controlling the position of the bar in the carriage, substantially as set forth.

36. In a paper-feeding machine, the combination of a paper-supporting table, with feeding-off devices comprising a reciprocating carriage, spring-pressed feeding-fingers pivotally mounted in the carriage, the vertically-movable bars or rods engaging the feeding-fingers at their lower ends, and carrying antifriction-rollers at their upper ends, a longitudinally-movable controlling-bar formed with a lower cam-face engaging said antifriction-rollers, means for confining said bar upon the carriage, and means for changing and controlling the position of the bar in the carriage, substantially as set forth.

37. In a paper-feeding machine, the combination of a support for a pile of sheets, with feeding-off devices comprising a reciprocating carriage, spring-pressed feeding-fingers pivoted upon the carriage, vertically-movable bars or rods having loose joint connection with the feeding-fingers, and an automatically-controlled cam-bar movably supported in the carriage in engagement with the bars or rods, substantially as set forth.

38. In a paper-feeding machine, the combination of a paper-supporting table, a reciprocating feeding-off carriage, a rack-bar movably supported in the carriage and formed with a lower cam-face, feeding-fingers pivotally mounted upon the carriage, vertically-movable bars or rods engaging the feed-fingers at their lower ends and carrying antifric-

tion-rolls at their upper ends which engage the lower cam-face of the rack-bar, a pawl or dog adapted to be thrown into engagement with the rack-bar, and means for automatically controlling the pawl or dog, substantially as set forth.

39. In a paper-feeding machine, the combination of a paper-supporting table, with a feeding-off device comprising a reciprocating carriage, the spring-pressed feeding-fingers pivotally mounted upon said carriage, the heels projecting from said fingers, the vertically-movable rods loosely engaging said heels, the rack-bar movable in the carriage and formed with a lower cam-face engaging the upper ends of the vertically-movable rods, an automatically-controlled dog adapted to engage and hold the rack-bar, and suitable stops adapted to engage and shift the rack-bar in the carriage at the ends of the stroke of the carriage, substantially as set forth.

40. In a paper-feeding machine, the combination of a paper-supporting table, a reciprocating feeding-off carriage, a pair of spring-pressed feeding-fingers pivotally mounted in the carriage and provided with heels, the vertically-movable rods engaging the heels of the feeding-off fingers, the bar formed with a lower cam-face engaging the upper ends of the rods and movably mounted in the carriage, and means for automatically shifting and controlling the bar in the carriage for elevating and lowering the feeding-fingers, substantially as set forth.

41. In a paper-feeding machine, the combination of a paper-supporting table, a reciprocating feeding-off carriage, a pair of spring-pressed feeding-fingers pivotally mounted in said carriage one in front of the other, the vertically-movable rods engaging the feed-fingers, the rack-bar movable in the carriage and formed with a lower cam-face engaging the vertically-movable rods, a dog mounted upon a stationary support and adapted to engage the rack-bar, an armature carried by the dog, an electromagnet, and an automatic contact-controlling device regulating the action of the magnet and actuated by the moving sheet of paper, substantially as set forth.

42. In a paper-feeding machine, the combination of the main frame having transverse bars, a paper-supporting table, adjustable brackets mounted upon the transverse bars and connected together, a track-bar secured to and extending between two of said brackets, a reciprocating feeding-carriage mounted upon said track-bar, an operating-lever connected with said carriage and journaled to one of the adjustable brackets, a cam-shaft, a cam adjustably mounted upon said shaft and arranged to actuate the operating-lever, and a fin or flange extending from one of the brackets and engaging the cam, whereby all of said parts can be adjusted as a single structure, substantially as set forth.

43. In a paper-feeding machine, the combination of the main supporting-frame having

transverse bars 2, 3, and 5, the brackets 171 and 172 adjustably mounted upon the bars 2 and 5, the track-bar 170 secured to and extending between said brackets, the bracket or casting 205 adjustably mounted upon transverse bar 3 and secured to the bracket 171, the bracket-arm 204 extending from bracket 205, the shaft 115, the sleeve 300 adjustably keyed to said shaft and formed with an annular groove, a fin or flange extending from one of the castings and engaging said annular groove, a reciprocating paper-feeding carriage mounted on the track-bar 170 and carrying feeding-off devices, an operating-lever pivoted to bracket-arm 204 and connected with the feeding-carriage, a cam secured to collar 300, and a driving rod or link connected with the operating-lever and supported in operative engagement with the cam, substantially as set forth.

44. In a paper-feeding machine, the combination of a paper-supporting table, suitable feeding-off devices, and a paper-separator comprising a stationary rubber-surfaced block supported in the plane of feed at the delivery end of the machine, a reciprocating carriage, a vertically-moving bar sliding in suitable guides in said carriage and supporting a vertically-moving reciprocating block, a rock-shaft journaled in the carriage and having a rock-arm at each end, one of said rock-arms engaging the vertically-sliding bar, an operating-lever connected with the other rock-arm, and stops on the carriage adapted to engage one of the rock-arms for limiting the oscillation of the rock-shaft, substantially as set forth.

45. In a paper-feeding machine, the combination of a paper-supporting table, and a vertically-movable paper feeding and separating device comprising a track-bar, a reciprocating carriage sliding thereon, a rock-shaft journaled in the carriage and provided with rock-arms on its ends, the feeding and separating block connected with one of said rock-arms, and adapted to be moved vertically thereby, an operating-lever connected with the other rock-arm, stops on the carriage adapted to engage one of the rock-arms for limiting the movement of the rock-shaft, and a brake-block carried by the carriage and engaging the track-bar, substantially as set forth.

46. In a paper-feeding machine, the combination of a suitable main frame having transverse bars 2, 3 and 5, a paper-supporting table, the brackets 171 and 172 adjustably mounted upon bars 2 and 3, the track-bars 170 and 261 secured to and supported between said brackets, the feeding-carriage 175 supported on track 170, the separator-carriage 262 supported on track 261, the bracket or casting 205 adjustably mounted on the transverse bar 3 and secured to bracket 171, the bracket-arms 204 and 285, extending from bracket 205, operating-levers 202 and 283 pivoted to the arms 204 and 285 respectively and connected with the carriages 175 and 262 re-

spectively, the shaft 115, the sleeve 300 adjustably keyed to the shaft and formed with an annular groove, a fin or flange extending from bracket 170 and engaging said annular groove, cams secured to said adjustable sleeve, and driving- rods operated by said cams and connected with the operating-levers 202 and 283, substantially as set forth.

47. In a paper-feeding machine, the combination of a paper-supporting table, paper-feeding devices for feeding sheets from the pile, sheet separating and propelling devices operating alternately with the feeding devices and located at the delivery end of the machine in position to receive sheets from the feeding devices, operating mechanism for the machine embracing an automatically-controlled clutch, and an automatic controlling device located at the delivery end of the machine in position to be operated by the sheets being fed off and adapted to actuate the automatic clutch for arresting the operation of the feeding devices and separating and propelling devices, as set forth.

48. In a paper-feeding machine, the combination of a paper-supporting table, sheet-buckling devices for effecting a preliminary separation of the sheets, paper-feeding devices for feeding sheets from the pile, sheet separating and propelling devices located at the delivery end of the machine in position to receive sheets from the feeding devices, operating mechanism for the machine embracing an automatically-controlled clutch, and an automatic controlling device located at the delivery end of machine in position to be operated by the sheets being fed off and adapted to actuate the automatic clutch for arresting the operation of the sheet-buckling devices, feeding devices and separating and propelling devices, as set forth.

49. In a paper-feeding machine, the combination of a paper-supporting table, paper-feeding devices for feeding sheets from the pile, sheet-separating devices located at the delivery end of the machine, drop-roller delivery mechanism adjacent to separating devices, means for operating the machine embracing an automatically-controlled clutch, an automatic controlling device located at the delivery end of the machine in position to be operated by the sheets being fed off and adapted to actuate the automatic clutch for arresting the operation of the feeding devices, separating devices and drop-roller delivery mechanism, as set forth.

50. In a paper-feeding machine, the combination of a paper-supporting table, and paper-feeding devices, with a main driving-shaft geared to the feeding devices, a power-gear loosely journaled upon the driving-shaft, a clutch member connected with said power-gear, a second clutch member keyed to the driving-gear and formed with a projecting head, a clutch-dog supported upon the second clutch member adjacent to its head, and a movable clutch-actuating device adapted to

disengage the clutch-dog from the clutch members and positively engage the head of the second clutch member for positively arresting the operation of the feeding devices, substantially as set forth.

51. In a paper-feeding machine, the combination of a paper-supporting table, paper-feeding devices, a driving-shaft geared to the feeding devices, a power-gear freely journaled upon the driving-shaft and carrying a clutch member, a second clutch member fixed to the shaft and formed with an enlargement or head, a clutch-dog pivoted to the clutch member adjacent to its head and formed with a heel which projects into the plane of the head, and a movable clutch-actuating device supported upon the machine-frame and adapted to be shifted into the path of the head and engage the heel of the clutch-dog and the head for disengaging the clutch and arresting the feeding devices, substantially as set forth.

52. In a paper-feeding machine, the combination of a paper-supporting table, paper-feeding devices, a driving-shaft geared to the feeding devices, a power-gear journaled upon the driving-shaft and carrying a clutch member, a second clutch member fixed to the shaft, and formed with an enlargement or head, a pivoted clutch-dog mounted upon the second clutch member, a sliding head 339 having arms 339^a and 339^b, pins 338 and 341 supporting said sliding head, an oscillatory shaft 342 journaled in suitable bearings and carrying a rock-arm 344 which engages arm 339^b of the sliding head, and means for operating the oscillatory shaft, substantially as set forth.

53. In a paper-feeding machine, the combination of a supporting-table, paper-feeding devices, a driving-shaft geared to the feeding devices, a power-gear, a clutch between the power-gear and driving-shaft, a movable clutch-operating device, an oscillatory shaft connected with the clutch-operating device, a weighted arm journaled upon said oscillatory shaft, an electromagnetic device engaging the weighted arm for holding it in elevated position, a rock-arm keyed to the oscillatory shaft adjacent to the weighted arm and adapted to be engaged thereby when said weighted arm is released, and a paper-actuated contact device for controlling the electromagnetic device, substantially as set forth.

54. In a paper-feeding machine, the combination of a paper-supporting table, paper-feeding devices, a driving-shaft geared to the feeding devices, a power-gear freely journaled upon the driving-shaft and carrying one clutch member, a second clutch member keyed to the driving-shaft, a clutch-dog, a sliding head adapted to disengage the dog from the clutch members, an oscillatory shaft carrying a rock-arm engaging said sliding head, a rock-shaft provided with operating hand-levers and suitably connected with said oscillatory shaft, a weighted lever freely journaled upon said oscillatory shaft, an arm keyed to the oscillatory shaft adjacent to the weighted lever, and

- adapted to be engaged thereby when released, an electromagnetic device controlling the weighted lever and a paper-operated contact device controlling the circuit of the electro-magnetic device, substantially as set forth.
55. In a paper-feeding machine, the combination of a paper-supporting table, suitable feeding devices, suitable driving mechanism, the drop-rollers mounted upon a suitable shaft geared to the driving mechanism, rock-arms supporting the drop-roller shaft, means for intermittently elevating and lowering the shaft and drop-rollers, lugs on the rock-arms supporting the drop-rollershaft, pivoted arms or levers carrying similar lugs adapted to engage the lugs on the rock-arms, and means for operating said pivoted arms or levers for holding the drop-rollers out of operative position, substantially as set forth.
- 10 56. In a paper-feeding machine, the combination of a paper-supporting table, suitable feeding devices, suitable driving mechanism, a clutch mechanism gearing the driving mechanism to the feeding devices, clutch-operating mechanism, the drop-rollers mounted upon a suitable shaft geared to the driving mechanism, rock-arms supporting the drop-roller shaft means for intermittently elevating and lowering the shaft and drop-rollers and suitable mechanism connected with the clutch-operating mechanism and adapted to raise the drop-rollers into operative position and hold them out of operation when the clutch is disengaged, substantially as set forth.
- 15 57. In a paper-feeding machine, the combination of a paper-supporting table, feeding instruments for feeding sheets of paper from the pile, and paper-separating devices disposed at the delivery end of the machine and adapted to separate the top sheet from the underlying sheet or sheets, with one or more resistance blocks or brakes resting constantly upon the paper at or adjacent to the rear edge and adapted to exert a frictional resistance to the under sheets of the pile while the top sheet is being fed off, substantially as set forth.
- 20 58. In a paper-feeding machine, the combination of a paper-supporting table, suitable buckling devices for effecting a preliminary separation of the rear corners of the sheets of paper, suitable feeding instruments for feeding the separated sheets from the pile, and paper-separating devices disposed at the delivery end of the machine, with one or more
- 25 resistance blocks or brakes resting upon the pile of paper at or adjacent to the rear edge, substantially as set forth.
59. In a paper-feeding machine, the combination of a paper-supporting table, suitable buckling devices, and feeding-off devices, with one or more holding-down blocks supported above the pile of paper, and operating means adapted to force the holding-down block or blocks into engagement with the pile of paper just in rear of the back edge of the top sheet being fed off, substantially as set forth.
60. In a paper-feeding machine, the combination of a paper-supporting table, suitable buckling devices, paper-separating devices disposed at the delivery end of the machine, and feeding-off devices, with one or more holding-down blocks supported above the pile of paper, and operating means adapted to force the holding-down block or blocks into engagement with the pile of paper just in rear of the back edge of the top sheet being fed off, substantially as set forth.
- 65 61. In a paper-feeding machine, the combination of a paper-supporting table, suitable buckling devices, one or more resistance blocks or brakes resting upon the top of the pile of paper at or adjacent to the rear edge, and feeding-off devices, with one or more holding-down blocks supported above the pile of paper, and operating means adapted to force the holding-down block or blocks into engagement with the pile of paper just in rear of the back edge of the top sheet being fed off, substantially as set forth.
- 70 62. In a paper-feeding machine, the combination of a paper-supporting table, suitable buckling devices, paper-separating devices disposed at the delivery end of the machine, one or more resistance blocks or brakes resting upon the top of the pile of paper at or adjacent to the rear edge, and feeding-off devices, with one or more holding-down blocks supported above the pile of paper, and operating means adapted to force the holding-down block or blocks into engagement with the pile of paper just in rear of the back edge of the top sheet being fed off, substantially as set forth.
- 75 63. In a paper-feeding machine, the combination of a paper-supporting table, suitable buckling devices, paper-separating devices disposed at the delivery end of the machine, one or more resistance blocks or brakes resting upon the top of the pile of paper at or adjacent to the rear edge, and feeding-off devices, with one or more holding-down blocks supported above the pile of paper, and operating means adapted to force the holding-down block or blocks into engagement with the pile of paper just in rear of the back edge of the top sheet being fed off, substantially as set forth.
- 80 64. In a paper-feeding machine, the combination of a paper-supporting table, suitable buckling devices, paper-separating devices disposed at the delivery end of the machine, one or more resistance blocks or brakes resting upon the top of the pile of paper at or adjacent to the rear edge, and feeding-off devices, with one or more holding-down blocks supported above the pile of paper, and operating means adapted to force the holding-down block or blocks into engagement with the pile of paper just in rear of the back edge of the top sheet being fed off, substantially as set forth.
- 85 65. In a paper-feeding machine, the combination of a paper-supporting table, suitable buckling devices, paper-separating devices disposed at the delivery end of the machine, one or more resistance blocks or brakes resting upon the top of the pile of paper at or adjacent to the rear edge, and feeding-off devices, with one or more holding-down blocks supported above the pile of paper, and operating means adapted to force the holding-down block or blocks into engagement with the pile of paper just in rear of the back edge of the top sheet being fed off, substantially as set forth.
- 90 66. In a paper-feeding machine, the combination of a paper-supporting table, suitable buckling devices, paper-separating devices disposed at the delivery end of the machine, one or more resistance blocks or brakes resting upon the top of the pile of paper at or adjacent to the rear edge, and feeding-off devices, with one or more holding-down blocks supported above the pile of paper, and operating means adapted to force the holding-down block or blocks into engagement with the pile of paper just in rear of the back edge of the top sheet being fed off, substantially as set forth.
- 95 67. In a paper-feeding machine, the combination of a paper-supporting table, suitable buckling devices, paper-separating devices disposed at the delivery end of the machine, one or more resistance blocks or brakes resting upon the top of the pile of paper at or adjacent to the rear edge, and feeding-off devices, with one or more holding-down blocks supported above the pile of paper, and operating means adapted to force the holding-down block or blocks into engagement with the pile of paper just in rear of the back edge of the top sheet being fed off, substantially as set forth.
- 100 68. In a paper-feeding machine, the combination of a paper-supporting table, suitable buckling devices, paper-separating devices disposed at the delivery end of the machine, one or more resistance blocks or brakes resting upon the top of the pile of paper at or adjacent to the rear edge, and feeding-off devices, with one or more holding-down blocks supported above the pile of paper, and operating means adapted to force the holding-down block or blocks into engagement with the pile of paper just in rear of the back edge of the top sheet being fed off, substantially as set forth.

TALBOT C. DEXTER.

Witnesses:

WM. E. KNIGHT,
M. V. BIDGOOD.
